UNITED STATES PATENT OFFICE.

TOLBERT LANSTON, OF WASHINGTON, DISTRICT OF COLUMBIA, ASSIGNOR
TO THE LANSTON MONOTYPE MACHINE COMPANY, OF SAME PLACE.

TYPE-CASTING AND COMPOSING MACHINE.

SPECIFICATION forming part of Letters Patent No. 633,088, dated September 12, 1899.

Application filed December 31, 1897. Serial No. 664,974. (No model.)

To all whom it may concern:

Be it known that I, TOLBERT LANSTON, a citizen of the United States, residing at Washington, in the District of Columbia, have invented certain new and useful Improvements in Type-Casting and Composing Machines; and I do hereby declare the following to be a full, clear, and exact description of the same, reference being had to the accompanying drawings, forming a part of this specification, and to the figures and letters of reference marked thereon.

This invention relates to improvements in or upon the class of type making and setting machines exemplified in Letters Patent No. 557,994, of April 7, 1896, wherein the individual types corresponding to or representing the matter to be composed or set up are successively formed in regular sequence and set up in justified lines, the justification being pre-arranged and automatically effected through the medium of a controlling-strip which governs the action of the type making and setting mechanisms.

Compared with the before-mentioned patented machine the present invention embodies distinct improvements in the means for controlling or governing the action of the type making and setting mechanisms employing a single instead of a multiplicity of controlling or record strips; in the composition and arrangement of the die-case and its actuating devices in the mold; in the mechanism for controlling the normal and justifying adjustments of the mold; in the pneumatic system through which the controlling-strip is caused to act upon and control the various mechanisms, and in other minor features hereinafter described, and set forth in the claims.

In the construction and practical use of machines of this class compactness, durability, speed, and accuracy of movement are of great importance, second only to capacity to perform the variety of operations required for the automatic production of justified lines of type, all of which qualities in addition to novel details of construction are embodied in the improved machine about to be described.

Before entering upon a detail description of the machine it will be of advantage to con-

sider briefly in a general way the principal operations performed and the results produced.

The present machine is one of two coördinate elements of the system, the other element including the means for and method of preparing the controlling-strip by which the operations of the machine are produced and governed. This controlling-strip is usually a single continuous web of paper provided at regular intervals with perforations, which latter are the active elements in determining the operations to be performed. Each type, whether character or space, has its representative in and is distinguished from all others either by the position or number of perforations, or both combined, and the types are divided into groups or classes according to the normal widths of the bodies, the latter corresponding with the size of lateral dimensions of the character or face. In addition to these character and space indicia there are certain other special perforations representing justification, line-feed movement, &c. The controlling-strip is prepared by forming at regular intervals the representative perforations for each letter, sign, character, space, &c., as it occurs in the composition. A special perforating-machine is preferably used for this purpose, one provided with automatic measuring devices, indicators, &c., whereby the space occupied by each character, &c., is added as the perforations are formed. As the end of the line is approached the operator is enabled to determine whether or not the next word or syllable will fill the line, and if not he is advised how much must be added to each space-type to just fill the line, whereupon the special perforations representing the amount of justification are formed, after which the special perforation or perforations for the end of the line is or are made, and the same process is gone through with for each succeeding line. The system of measurement and the location of the perforations are predicated upon the employment of character and space types of fixed dimensions—that is to say, the width of each character-type is proportioned to the width of its character or device—and the space-types are measured as of normal or fixed dimensions,

according to a predetermined scale or system of measurement. The space to be filled by justification in each line is distributed in this machine equally among the several space-types; but it is obvious provision can readily be made for distributing it among all or any particular series of the types to be made. As before indicated, the perforations in the controlling-strip, which determine the amount to be added to each space-type in the line to just fill out or "justify" said lines, are produced after the helps for the character, spaces, &c., composing the lines have been formed, and as these justification-perforations are to control the preceding matter the machine is organized to be operated upon by the controlling-strip, as the latter is fed in the opposite direction from that in which it was formed—that is to say, beginning at the last end of the last line. Having thus indicated in a general way the make up of the controlling-strip, it is in order to explain the machine with which it is designed to coöperate. For convenience of description the mechanism may be considered under various heads corresponding with the special operations performed.

The machine being organized for casting separate types, it is furnished with a series of dies or matrices corresponding with the number and variety of characters to be employed and with actuating devices competent to bring and hold any given matrix to the casting position, where it forms temporarily one end of the mold. This mechanism, designated the "die-case" or "matrix," and its actuating mechanism includes a group of matrices supported to move horizontally and controlled in its movements by two sets of mechanism acting at right angles or in transverse planes to determine by their joint action the position of each matrix, said position being the resultant of two motions in transverse planes and determined by the length of transverse communicated by each set of devices acting thereon. One novel feature of this mechanism resides in the devices whereby the movements are produced and determined, the same comprising fixed ratchets, reciprocating pawls, and stop-pins engaging the pawls to throw into contact with the fixed ratchet-plates, and thus arrest the movements of the die-case without unnecessary shock or pressure upon the stop-pins, the latter serving merely to initiate the stopping action.

In addition to the motions described for bringing the matrices to the casting or impression point there is a further provision for insuring the centering of the selected matrix or die and for holding it firmly against the end of the mold. The special function of this mechanism is to bring any one of a series of dies or matrices into position, to center it accurately, and to depress or hold it firmly in adjusted position, and subsequently to return the series to initial position preliminary to the selection of the next character. It will

be obvious that this portion of the mechanism can be utilized in connection with other devices for printing, matrix-making, and similar purposes, the form and dimensions of the type or matrix being such as the character of the work to be performed render necessary or desirable.

Beneath the die-case and in line with the centering-point for the series of dies or matrices is the mold in which the body of the type is cast, the printing end of the type being formed by the selected and centered matrix closing the upper end of the mold-cavity. This mold is furnished with a movable blade whose end constitutes one wall of the cavity, and this blade is controlled as to position by devices connected with the mechanism for actuating the die-case, so as to automatically effect an adjustment of the mold-cavity to correspond with the width of the selected character—that is to say, as each matrix is centered the movable blade is adjusted to produce a mold-cavity of a width corresponding with that of the character selected. The foregoing adjustments of the mold and the mechanism for effecting them are termed "normal," as they are dependent upon and accompany the selection of each character or space-die; but there is another series of adjustments made operative through the same movable blade, which are termed "abnormal" or "justifying" adjustments. These last-named adjustments are determined and fixed for each line and are made operative to vary the normal size of the mold when each space-type of a line requiring justification is to be cast. Thus should the associated character and space-types, if of normal width, fall short of filling the line by, say, sixty-thousandths of an inch, leaving the amount to be filled by justification, and there were six space-types in said line, the abnormal adjustments of the movable blade would be such as to add ten-thousandths of an inch to each space-type. The mechanism for effecting this abnormal adjustment is independent of, but operates in part through, the normal adjusting mechanism.

At the moment the mold is adjusted as to width, either normal or abnormal, and the matrix is centered and held firmly in position upon the top thereof molten type-metal is injected from below to fill the mold and form the type. This operation is performed by what is designated the "pump-and-pot" mechanism, comprising a melting-pot, with nozzle, and pump, the whole pivotally supported, so that the nozzle will be brought into position beneath the mold and the pump operated to inject molten metal therein. The type as produced are delivered to the galley mechanism, by which latter they are assembled in line and the lines arranged in column form ready for removal. The general *modus operandi* is as follows: As each type is pushed from the mold it is received in a carrier, moved laterally into line with a receiving

channel, and is immediately discharged into said receiving-channel by a pusher. Provision is made for supporting the types in upright position during their movement through 5 the receiving-channel, and when a line is completed the types composing said line are moved together opposite a galley and thrust therein. Means are provided for retaining the types in alinement and in vertical position during these several movements of the line, and automatic tripping devices are arranged to arrest the movement of the machine in the event the line is either above or below the standard as to length.

15 The next and one of the most important elements of the machine comprises the controlling means or system whereby the movements of the several mechanisms are produced and governed. This includes the pneumatic controlling system and the paper-feed or devices directly coöperating with the perforated controlling-strip. The paper-feed regulates the movements of the perforated controlling-strip *h h*, its principal function 20 being to advance the strip intermittently and present and hold each successive section containing one or more perforations in operative position with relation to the pneumatic controlling system. The pneumatic system includes a pressure-supply main with a controlling-valve operated by the paper-feed devices to open communication and supply 25 fluid-pressure when the strip has been properly located in position. A series of air-ports corresponding in number and position with the spaces assigned for perforations in the controlling-strip are so arranged that at 30 the completion of each feed movement of the controlling-strip a section of the latter containing a perforation or perforations representing definite movements of some of the mechanism will be brought into alinement with the ports, the perforations registering 35 with corresponding ports and the unperforated sections closing the remaining ports, whereby the selected passages will be placed 40 in communication with the air-supply and will be charged with air or other fluid under pressure upon the opening of the controlling- 45 valve.

50 Certain of the air-ports are connected with and control the movements of the stop-pins of the die-case-actuating mechanism for centering the dies or matrices, while others control the action of the justifying devices, the galley mechanism, and incidentally the pump and resetting devices. For example, assuming the line to be cast requires justification, if types of normal size are employed the first 55 operation will be to set the justifying mechanism for this line, which will be accomplished by the perforation or perforations in the first section of the controlling-strip opening communication with the justifier mechanism. As the motion of the driving-shaft is utilized in effecting this adjustment, it becomes desirable to interrupt the casting op-

eration while the adjustment is being effected, and this is accomplished automatically by the admission of air under pressure to control a part in the line of communication between the driving-shaft and the pump. After the adjustment for justification has been made the operation of forming types is begun and carried on; but the justification adjustment is held inoperative thereon and is not brought into action until a space-type is reached. Whenever this occurs, a passage leading to the justifying mechanism is opened and the latter is automatically connected to the movable blade of the mold, so as to control the position of said blade and determine the size of the mold. When the last type composing the line has been formed and it becomes necessary to transfer the completed 85 line to the galley, the galley mechanism is set in action by a perforation controlling a part in the line of connection with the driving-shaft. At the same time the pump is thrown out of action and the resetting devices are set in motion for returning the justifying mechanism to normal position preliminary to beginning the next line.

The foregoing brief explanation is not intended as a specification of the novel features 95 of the machine, but rather as a prelude to a detail description of the mechanism, the novel features whereof are specified in the appended claims.

Referring to the accompanying drawings, 100 Figure 1 is a view in perspective of the machine, looking toward the latter from the left front corner. Fig. 2 is a top plan view of the machine, a small section of the justifying mechanism being omitted. Fig. 3 is a front 105 elevation. Fig. 149 110 is a front view of cam-cylinder containing cam-groove for reciprocating melting-pot and nozzle. Fig. 150 shows the opposite face of cam-cylinder, Fig. 149, containing cam-groove for the paper-feeding devices. Fig. 151 shows 115 the cam-groove for the operating-lever of the left-hand die-case-actuating mechanism. Fig. 152 is an end view of the cam-cylinder containing the cam-groove which controls the transfer of the line from the line-channel 120 to the galley. Fig. 153 is an edge view of the cam-cylinder, Fig. 152, showing the cam-groove for effecting the longitudinal reciprocations of the line-carrier. Fig. 154 is an end view of the cam-cylinder containing the 125 cam-groove for operating ejector to transfer type from the type-carrier to the line-channel. Fig. 155 is an edge view of the cam-cylinder, Fig. 154, showing cam-groove for reciprocating justifier-slide. Fig. 156 shows 130 the cam-groove for reciprocating the mold-blade. Fig. 157 is a view of the cam for producing the reciprocating movements of the rear die-case-actuating mechanism. Fig. 158

is a side elevation of the fast pulley, showing the cam for operating the plunger for centering and depressing the matrix-blocks. Fig. 159 is a side view of the cam-cylinder containing the cam-groove for operating the rule or blade. Fig. 160 is a view of the opposite side of cam-cylinder, Fig. 159, showing the cam-groove for controlling the lateral movements of the line-carrier.

10 Like numerals and letters of reference in the several figures indicate the same parts.

The general arrangement and relative locations of the several mechanisms will be best understood by reference to Figs. 1 to 8, inclusive. All the operating devices are supported upon a main frame or base 12, which latter is preferably made hollow to accommodate part of the mechanism. All the working mechanisms derive motion from a main driving-shaft 13, formed in two sections connected to rotate in unison by beveled gears 14, one section of said shaft—that carrying the fast and loose driving-pulleys 15 and 16—being supported in bearings on the rear of the frame, 20 while the other section is supported on the left-hand side of the frame. The mold occupies a central position on top of the frame, and above it is the die-case, whose actuating mechanisms extend the one to the left and 25 the other in rear of the mold. The pump and melting-pot are located to the right of the mold, the nozzle projecting beneath and in line with the mold-cavity. The galley mechanism occupies a position in front of the mold. 30 The paper-feed and the portions of the pneumatic system directly controlled thereby are located in rear and to the left of the mold, standing somewhat above the general level of the machine.

35 *The die-case or matrix and its actuating mechanism.* — This mechanism comprises those parts of the machine, considered as a whole, which serve to control and effect the movement which determines the form or character of the face of each type made on the machine—that is to say, it serves to bring any one of the several matrices employed in proper relation to the mold, to center the selected matrix, and to press and hold the latter firmly in position upon the end of the mold. It will be obvious that the same mechanism is adapted for use in other machines—such as printing, matrix-making, and similar apparatus—where it is desired to bring any 55 one of a series of characters or punches to a common center or impression-point.

The die-case proper, 26, (shown detached in Figs. 14, 15, and 22 and in position in Figs. 1, 2, 3, 7, 8, 10, and 11,) is composed of an open 60 rectangular frame 17, provided with opposite guides or ribs 18 and an eye 19. The opening in frame 17 is occupied by a series of independent blocks or matrices 20. These blocks are angular or square in cross-section 65 and are arranged in parallel columns, as shown in Fig. 22. The various characters comprising the selected font are represented

each by a die-cavity or matrix formed in one of the blocks 20, and in arranging the various matrices in the die-case these characters, 70 which are accorded the same width, are arranged in the same line. Thus in the example illustrated in Fig. 22 the narrowest type are represented in the bottom line, opposite which is placed the figure "1." The next 75 larger size types are arranged in the second line, and so on, the largest types being arranged in the top line, numbered "11." It will be seen that in this particular instance the characters are divided into eleven different sizes. Hence the types produced will be of eleven different dimensions. The matrix-cavities formed in the ends of blocks 20 may be made in any desired or preferred way, 80 and in the example illustrated in Figs. 15, 85 16, and 17 they are formed by first slotting the end of the steel block transversely, inserting a soft-metal section 21 within the slot, and forming by pressure a cavity and matrix surface, two walls of said cavity being of 90 steel or hard metal and the other two walls of the softer metal, such as copper. Any suitable mode of forming the matrices may be employed. Each matrix-block 20 is furnished with a conical recess 22 in its rear 95 end—that is, the end opposite the matrix—and it is also provided with a transverse opening 23 to receive a sustaining-pin 24. Each row of matrix-blocks is strung upon one of the pins 24, (see Fig. 15,) the ends of the pins 100 resting in cavities formed in the frame of the die-case and being held in position by bars 25. The matrix-blocks 20 are fitted snugly within the frame of the die-case, so as to be held in position therein, and are permitted a 105 slight degree of independent longitudinal motion just sufficient to permit the end of the matrix-block to seat squarely and firmly upon the mold when pressed down by the centering-plunger. This limited independent movement of the matrix-blocks in the die-case is provided for by making the transverse openings 23 slightly larger than the sustaining pins or wires 24, so that when the die-case is 110 depressed and the selected matrix is brought down against the end of the mold to close the latter the pressure will be transmitted wholly 115 through the selected matrix-block, and in the event dirt, dust, or any foreign substance should find lodgment on the mold beyond 120 the margin of the selected matrix the engagement of any matrix-block other than the selected matrix instead of arresting the latter, and thus preventing the closing of the mold, would merely operate to hold back said 125 matrix-block, permitting the selected matrix-block to descend until fully seated on the end of the mold. When the die-case is again elevated and the centering-plunger withdrawn, the matrix or matrices that have been thus 130 held back during the seating of the selected matrix are free to resume their former position under the influence of gravity, and if they do not the displacement is so slight that

it will in no way interfere with the action of the centering-plunger, which latter when brought opposite the slightly-elevated matrix will push it down into close contact with the mold.

It will be noted that the die-case illustrated in Fig. 22 contains eleven horizontal lines of matrix-blocks, the individuals composing the several lines being arranged in twelve vertical columns, (lettered *a* to *l*.) The die-case 26 is supported in an open frame 27, Fig. 13, the latter being provided with side grooves 28 to receive the guides or ribs 18 of the die-case. Above the grooves or guides 28 of the supporting-frame and at right angles thereto are arranged a pair of guides 29, adapted to fit guides 30, formed upon the opposite edges of a supporting-plate 31, Fig. 18. This supporting-plate 31 is provided with a central aperture 32, and is secured to the lower ends of two vertical rods 33, (seen best in Fig. 8,) connected at their upper ends by a yoke 34 and passing through a head 35, Fig. 20, which is detachably secured to a fixed part 36, Fig. 19, of the framework. Springs 37, surrounding rods 33 above the head 35, serve to hold the supporting-plate 31 and its attachment normally in an elevated position, at the same time permitting a limited vertical movement of said supporting-plate, carrying with it the die-case 26 and intermediate frame 27.

By reference to Figs. 8, 11, and 20 it will be seen that the head 35 is furnished with a central guide 38, the lower portion of which is composed of a cylindrical hub or extension 39, having its lower end tapered and slotted transversely, while its upper portion is screw-threaded to receive a nut 40, having a tapering aperture at one end and coöperating with the tapered end of the hub 39 to spring the slotted portion and thus adjust the size of the lower end of the opening or guide. Working within the guide 38 is a vertical plunger 41, whose lower extremity is provided with a conical centering-pin 42, adapted to enter the conical seat 22, formed in the rear end of each matrix-block 20, thereby insuring the centering of each matrix-block preliminary to its depression upon the top of the mold. After the conical centering-pin 42 has fully entered the recess 22 in the matrix-block, and has thus brought the matrix accurately into position, a further descent of the plunger 41 will cause it to depress the matrix-block, carrying with it the die-case, its carrying-frame, and supporting-plate. The vertical movements of the plunger 41 are transmitted through a lever 43, Figs. 1, 2, 5, 6, and 7, one end of said lever being engaged by a cam 44, Fig. 158, on the side of fast pulley 15, while the opposite end of said lever is bifurcated and embraces a sleeve 45, Fig. 21. This sleeve 45 is fitted loosely to the upper end of plunger 41, between fixed collars 46, carried by said plunger, and a spring 47 is interposed between the lower fixed collar 46 of the movable sleeve 45,

so that when the lever is operated to depress the plunger it will transmit the pressure through the spring, and the latter being heavier, and consequently stronger, than the two springs 37, supporting the die-case and its attachments, when the end of the plunger 41 has become seated in the rear face of the matrix-block it will carry the latter downward against the resistance of springs 37.

One object of the spring 47 is to prevent breakage in the event some foreign material should be interposed between the matrix-block and the mold or in the event that through some accident the movements of the die-case should be interrupted so as to prevent the proper presentation of a matrix beneath the plunger.

It is desirable that springs 37 should be of such strength compared with spring 47 as to uphold and support the die-case until the plunger shall become fully seated in the matrix-block, thereby centering the latter accurately before depressing it.

It is next in order to consider the mechanism controlling the movements of the die-case for bringing any one of the series of matrix-blocks into position beneath the plunger 47.

It will be remembered that the die-case is permitted two movements at right angles to each other—the one (that of the die-case) in or upon its supporting-frame 27 and the other (that of the supporting-frame 27) upon the supporting-plate 31. The movements of the die-case upon its supporting-frame are in a direction front and rear of the machine and embrace the successive columns marked *a* to *l*, inclusive, Fig. 22. These motions are derived from the controlling or actuating devices located in rear of the die-case, as shown in Figs. 1 and 2. The movements of the supporting-frame 27, corresponding with the successive lines of matrix-blocks 1 to 11, inclusive, Fig. 22, are controlled by the mechanism to the left of the die-case. It will be obvious that through these two movements at right angles any particular matrix-block in the series can be brought into position beneath the plunger 41. When not in action, the die-case stands normally at the front extreme of its movement in its supporting-frame and with the latter at the right extreme of its movement upon the supporting-plate, thus bringing one corner of the frame 17 beneath the plunger 41, Figs. 5, 7, 8, and 10. In order that each matrix-block may be brought into position, it is necessary to provide as many degrees of movement in one direction as there are lines of matrix-blocks in the die-case and as many degrees of movement in the transverse direction as there are columns in the die-case. For example, with the die-case illustrated in Fig. 22 there are required eleven degrees of movement in one direction, corresponding to the lines 1 to 11, and twelve degrees of movement in the other direction, corresponding to the columns *a* to *l*, inclusive.

We will first consider the left-hand controlling mechanism operating to shift the supporting-frame 27 upon its supporting-plate to bring successive lines of matrix-blocks into position in line with the plunger. To a lug 48 on said supporting-frame 27 is pivoted one end of a link 49, Fig. 8, whose opposite end is pivotally connected to a slide 50, Fig. 25, supported to reciprocate in ways 51, secured to the frame of the machine. A horizontal lever 52 has its front end connected to slide 50 by a link 53, and motion is communicated to said lever in a direction to reciprocate slide 50 by a lever 54, carrying a pin riding in a cam-groove 54^X, Fig. 151, formed in the face of the beveled gear 14 on the rear end of the left-hand section of driving-shaft 13, the upper end of said lever being pivotally connected to a rod 55, supported to a slide in a bearing at its inner end and carrying roller 56, preferably of rawhide or other shock-reducing material, engaging one side of lever 52, as shown in Figs. 1, 2, and 53. The lever 52 is held under yielding pressure against the roller 56 by a spring 57, connected at one end to said lever and at the opposite end to the rod 55. The cam-groove 54^X, Fig. 151, acting upon the driving-lever 54, is of such form that at each rotation of the driving-shaft it will effect one complete reciprocation of slide 50 and of the supporting-frame 27, connected thereto and carrying the die-case 26, the motion in one direction, effected by the engagement of roller 56 with lever 52, being positive, while the motion in the opposite direction, from right to left, being transmitted through spring 57, is subject to variation as to extent without interfering with the uniform excursions of lever 54, the latter making a full reciprocation for each revolution of the main driving-shaft. With this mechanism it is only necessary to provide adequate means for arresting the movements of the slide 50 at certain predetermined intervals during its excursion from right to left in order to bring any one of the lines of matrix-blocks into alignment with the centering and depressing plunger 41. To accomplish this result, a series of stop-pins 58 or equivalent devices are employed, they being located in the path traversed by the slide 50 or some part connected therewith, said stop-pins being so arranged that each one when projected into the path of the slide 50 will arrest the latter at such a point in its movement as to bring one of the lines of matrix-blocks in alignment with the plunger. It is obvious that the stop-pins may be arranged in a variety of ways for accomplishing this result; but the arrangement shown in the drawings is preferred in that it effects economy of space and movement and reduces shock and wear on the stop-pins. By reference to Figs. 1 and 2 it will be seen that the stop-pins are in two series and located on opposite sides of the slide 50, there being six pins on one side and five on the other, making eleven stop-pins in all, corresponding

with the eleven lines of matrix-blocks, as represented in Fig. 22. All of the stop-pins 58, with the exception of the one located at the extreme left end of the series, are movable through guides or openings formed in plates 59, arranged above and forming the upper portion of the ways 51, in which slide 50 reciprocates, and the stop-pins are arranged in series at equal distances apart, measured in the direction of the movement of slide 50, the distance between successive stop-pins in the series being just equal to the width of the matrix-blocks in the die-case or the distance from center to center of contiguous matrices. The slide 50 is provided with two pivoted pawls 60, Figs. 10 and 11, each arranged to coöperate with teeth 61, formed on one of the plates 59. The two pawls 60 operate in opposite directions and are held retracted or from contact with the teeth 61 by a spring 62, arranged intermediate the operating ends of the pawls and their pivots. Each pawl 60 is provided with an arm 63, projecting laterally over the corresponding plate 59. Normally all the stop-pins 58, except the last one, stand with their bodies retracted and their upper ends at or below the surface of plates 59, so as to offer no obstruction to the movement of the pawl-arms 63 over plates 59 until the last or fixed pin in the series is reached, when the arm 63 will engage said pin and throw the pawl into engagement with the last tooth 61 on that side, thereby arresting the movement of slide 50 as line 1 of matrix-blocks, Fig. 22, is brought into alignment with the plunger. To arrest the movement of slide 50 at any intermediate point, it is only necessary to project one of the movable stop-pins while the slide 50 is at or near the right extreme of its movement, so that upon the next movement to the left it will be engaged by one of the pawl-arms to throw the pawl into engagement with the corresponding tooth 61. The engaging faces of the ratchet-teeth 61 are formed at somewhat less than a right angle to the plane of movement of the slide carrying the pawls, and the engaging end or point of each pawl 60 is correspondingly inclined, so that when the pawl is turned by the stop-pin sufficiently to bring its point opposite a tooth and it is caused to contact with the inclined face of the tooth the arm will be thrown to one side and away from the stop-pin, thereby preventing the stop-pin from receiving the blow incident to the arresting of the slide by the contact of the pawl with the ratchet. It will be observed that with this mechanism the pins merely operate to throw the pawls into engagement with the ratchet-teeth and that the shock incident to the sudden arresting of motion is borne by the pawls and ratchet-teeth rather than by the stop-pins themselves.

From the foregoing description it will be seen that each line of matrix-blocks 1 to 11, inclusive, is represented by one of the stop-pins 58, that the movement of the die-case

from the normal or starting position is effected through an elastic connection such as will permit the arresting of the slide 50 at an intermediate point while the driving mechanism continues and performs its full excursion in one direction, that the return of the die-case to its normal or first position is effected by a positive connection with the driving mechanism, and that the arrest of the die-case during any portion of its traverse away from the starting-point is under the control of the series of stop-pins and is effected by the immediate contact of the stop-pawl engaging the fixed tooth corresponding with the selected stop-pin.

The forward and back movements of the die-case to bring any one of the columns of matrix-blocks *a* to *l*, Fig. 22, into alinement with the plunger are effected by reciprocating the die-case in its supporting-frame 27. With this end in view a link 64 is pivotally connected at its front end to the eye 19 on the frame of the die-case, the rear end of said link engaging a rod 65, detachably supported in adjustable bearings attached to a slide 66, Figs. 2, 7, 10, and 23: The rod 65 is of a length to permit the link 64 to slide thereon during the movements of the supporting-frame and die-case before described, at the same time it forms the connection through which the motions of the die-case in its supporting-frame at right angles to the movements of the latter are produced. The slide 66 is mounted to reciprocate in guides 67, each of which is surmounted by a pin-plate 68, provided with stop-pins 58 and teeth 61, similar to those before described, except in this instance an additional stop-pin is added, as there are twelve columns, *a* to *l*, inclusive, in the die-case. In other words, there is a stop-pin for each column in the die-case, the rearmost pin, corresponding to the last column in the die-case, being fixed, while the other pins are movable. Slide 66 is in like manner provided with two pawls 60, each provided with an operating-arm 63 and connected by a retracting-spring 62, and the operations for arresting the slide 66 to bring any given column of matrix-blocks into alinement with the plunger is effected by elevating the stop-pin corresponding to the selected column in the die-case and causing it to operate the arm of the pawl during the rearward movement of the slide to throw the pawl into engagement with one of the teeth on the pin-plate. The movements of the slide 66 are produced by a cam 69, Fig. 157, acting upon a lever 70, whose upper end is pivotally connected to the rear ends of two parallel bars 71, whose front ends are pivoted to opposite sides of a sleeve 72, supported upon a rod 73. The front end of this rod 73 is connected by a vertical bolt 74 to a boss 75 on slide 66, Figs. 7 and 23. A spring 76 connects the rear ends of bar 71 and the bolt 74 on slide 66. Spring 76 forms an elastic connection between slide 66 and its actuating-lever 70, which permits

the slide to be arrested while the lever continues its outward or rearward movement, at the same time the contact between sleeve 72 and the head of rod 74 forms a positive connection for returning the slide 66 to its forward or normal position.

From the foregoing description it will be obvious how any one of the matrix-blocks 75 may be brought into position beneath the plunger during each complete revolution of the driving-shaft, the position of slide 50 as controlled by its stop-pins determining the line and the position of slide 66 as controlled by its stop-pins determining the column in which the selected matrix-block is located. For example, suppose it is desired to bring the matrix-block bearing the figure 4, Fig. 22, in position beneath the plunger. 85 This particular matrix-block is found in the ninth line, counting from the top, and the seventh column, counting from the left. If the ninth stop-pin of the left-hand series and the seventh stop-pin of the rear series are simultaneously elevated and the driving-shaft is set in motion, the die-case will be moved to the left until the ninth line is reached and to the rear until the seventh column is reached, and as a resultant to these two motions the matrix-block carrying the character 4 will be located in position beneath the plunger and there held while the plunger descends to first accurately center and then depress the selected matrix-block.

The mold and its normal adjustments.—The mold is arranged to be automatically adjusted to suit the width (setwise) of the type to be formed, the selected matrix-block being held in contact with the upper end of 105 the mold and forming the top thereof, and the molten metal to form the types being injected through an opening at the base of the mold-cavity. The details of the mold and the relative arrangement of its parts are best observed in Figs. 7, 8, 32, 34, 35, 36, 37, 38, 77, and 80.

To the frame of the machine is attached a bed-plate 77, containing the nozzle-seat 78, located directly below and in line with the plunger 41. Upon the upper face of the bed-plate 77 is formed or secured a transverse bar or ledge 79, whose front face forms one side of the passage leading from the pump-nozzle to the mold-cavity. To the top face of this bar 79 are secured two blocks 80 81, their proximate vertical faces forming two sides of the mold-cavity. The block 80 is adjustably attached to its supports, and the block 81 carries projecting from its face a rib adapted to form 125 the nick in the body of the type. This rib may be formed integral with block 81 or be detachably secured thereto. The front wall of the mold-cavity is formed by the vertical face of the block 83, Fig. 35, attached to 130 what is termed the "jet-slide" 84, so called because it contains the recess or passage through which the metal is driven in its passage to the mold and in which the jet or

block of surplus metal is formed below the mold. This jet-slide rests upon the bed-plate 77 and is adapted to reciprocate in a channel formed between the bar 79 and blocks 80 81 at the rear and the fixed block 85 at the front. (See Fig. 80.) Set-screws passing through the fixed block 85 and bearing against a wearing-plate 86 serve to hold the block 83 in close contact with the front ends of blocks 80 81. The blocks 80 81 project slightly forward beyond the front face of bar 79, thus forming a recess to receive the lower portion 87 of jet-slide 84, said portion projecting laterally beyond the vertical face of block 83, Fig. 35. In the lower face of slide 84 is formed a transverse groove or recess 88, extending through the projection portion 87, said groove being adapted to receive a block or slide 89, Fig. 36. This block or jet-blade 89 is triangular in cross-section and is provided with a groove 90 to receive a cam-block 91, fixed to the bed-plate 77. When the jet-slide 84 is in position in front of the blocks 80 81 and a type is being cast, that portion of groove 88 extending through the projecting portion 87 of the slide will stand in line with the pump-nozzle and the open space between blocks 80 81. At the same time block 89 will be retracted or withdrawn from the groove in projecting portion 87, so as to leave a passage through which the jet of molten metal may enter the mold, Fig. 32, and in which passage the jet or block of surplus metal is formed. When, however, slide 84 is withdrawn to the right to uncover the front of the mold-cavity by withdrawing block 83 from in front of blocks 80 81, the jet formed in said passage during the casting operation will be severed from the type, and the block 89 by its engagement with cam 91 will be forced outward—that is, toward bar 79—thereby ejecting the jet and discharging it into an orifice 92, formed in bar 79 and bed-plate 77, as seen in Figs. 33 and 38. The movements of jet-slide 84 are produced and controlled by a cam 93, Fig. 147, acting on a lever 94, the latter connected by a rod 94^x with a lever 95, whose upper end is connected by a link 95^x to said slide. Thus far we have considered only three of the four side walls of the mold-cavity—to wit, the two fixed walls formed by blocks 80 81 and the movable front wall formed by block 83. The rear wall of the mold-cavity is formed by the front end of the mold-blade 96. This mold-blade is fitted accurately between blocks 80 81, and constitutes the medium whereby the width of the mold-cavity is adjusted to produce type of normal or standard width, but of varying size, according to the characters they bear. It is grooved on the side to receive the nick-forming rib 82 and is held and guided in its movement as by plates 97, Fig. 38, secured to a block 98, the latter being provided with a recess 99 for the accommodation of the mold-blade and secured in position upon the bed-plate 77 in rear of bar 79 thereon.

The mechanism controlling the position of

the mold-blade 96 comprises two series of actuating devices, the one operating to effect the movements of the mold-blade and the other to measure or control its position. The actuating devices which produce the movements referred to operate through a slide 100, to which the rear end of the mold-blade is secured, and they include a retracting-spring 101, operating to draw the slide rearwardly against the front face of a lever 102, working in a slot 103, formed in said slide. To the lower end of this lever is pivotally attached one section of a telescopic link 104, the opposite section of said link being pivotally attached to a lever 105 at a point intermediate its fulcrum and the point of attachment of a rod 106, the latter bearing a yoke 107, embracing the rear section of the main driving-shaft 13 and carrying a pin engaging a groove in cam 108, Fig. 156. Between a collar 109 on the section of the telescopic link attached to lever 102 and a pin 110 borne by the opposite section attached to a lever 105 is a compression-spring 111, through which motion is transmitted from lever 105 to lever 102 in a direction to carry the mold-blade forward between the blocks 80 81, which movement takes place after the type-casting operation has been finished, the front wall of the mold has been withdrawn to one side, and the finished type is to be delivered to the type-carrier. After the type has been thus ejected from the mold the mold-blade is drawn back by the action of spring 101 as lever 102 is vibrated on its pivot by the action of its controlling-cam 108. The forward movement of the mold-blade to eject the type is adjusted and limited by the contact of the shoulder or screw 113 on slide 100 with an adjustable stop-plate 114 on the frame. As thus far described, it will be seen that the mold-blade would be incompetent to form type of other than fixed dimensions, as its return movement after ejecting the previously-formed type would always be of the same extent. It is by controlling automatically the extent of the return movement of the mold-blade after having ejected a type that the adjustment of the mold-cavity is effected, and to permit this the slot 103 in slide 100 is made longer than the head of lever 102, so that said lever may be permitted a limited movement in the slot when the slide is arrested during the back stroke. The mechanism for measuring or controlling the position of the mold-blade includes the part termed the "normal wedge" 112 and its connections. (See Figs. 2, 7, 39, 40, 41, and 42.) Slide 100, Fig. 27, to which the mold-blade is attached, is provided with a socket 115 for the reception of one end of a rod 116, whose opposite or rear end is adjustably attached to a sliding block 117, to which is fitted a vertical pin 118. The slide 117 is fitted to reciprocate in a direction longitudinal of rod 116, within a guide or recess 119, formed in a plate or frame 120. This plate 120 is furnished with two transverse guides 121, be-

tween which is received the normal wedge 112. This wedge 112 is constructed in the form of a slide, having parallel guiding edges which coöperate with guides 121 on plate 120, 5 and in its under surface is formed or provided a groove or way 122, disposed at a slight angle to the plane of guides 121. To the pin 118 is fitted a block 123, the latter fitting accurately between the walls of the inclined 10 groove or way 122. It will be observed that the groove 122 in slide 112 operates upon slide 117, through its pin 118 and the block 123 after the manner of a wedge, and that whenever this normal wedge 112 is moved longitudinally upon its supporting-plate 120 it 15 will operate to shift rod 116 longitudinally. The angle of inclination of groove 122 to the guides 121 and its range of motion are such as to produce a longitudinal movement of the 20 rod 116 equal to or greater than the difference between the narrowest and widest types to be produced, including within these extremes all the intermediate variations in 25 width. It will be apparent, therefore, that by shifting the normal wedge 112 in the proper degree it will project and hold rod 116 in such relation to slide 100 carrying the mold-blade that upon the backward or return movement of said slide after a type has been ejected the 30 rod 116 will arrest said slide and hold it in position to form a mold-cavity of the desired width, such width depending upon the position which the normal wedge occupies for the time being within the limits of movement of 35 said wedge. It will be remembered that the lines of matrix-blocks 1 to 11, inclusive, Fig. 22, in the die-case represent different widths of types and that the shifting of the die-case from right to left to bring successive lines of 40 matrix-blocks into alinement with the plunger is equivalent to moving the series of matrices belonging to types of maximum width to the series of matrices belonging to types of the next smaller degree, and so on throughout 45 succeeding lines of matrix-blocks in the die-case. It is therefore only required that the movement imparted to the normal wedge 112 shall correspond or be proportional to the movements imparted to supporting-frame 27 50 of the die-case for bringing successive lines of matrix-blocks into alinement with the plunger, which movements are controlled by the left-hand series of stop-pins 58, as hereinbefore described. Accordingly the rear end 55 of lever 52 is connected by a link 124 to the end of normal wedge 112, whereby said wedge is caused to move in exact unison with slide 50 and the supporting-frame for the die-case. In order to afford means for accurate adjustment of the normal wedge 112 and through it of the stop-rod 116, a micrometer, indicating ten-thousandths of an inch, is applied to the connecting-link 124. The preferred form is 60 illustrated in Fig. 52, wherein the link is shown as formed in two sections whose proximate ends are provided with right and left hand screw-threads, respectively, connected

by a right and left hand threaded sleeve 125. A stop-nut 126 is arranged at each end of sleeve 125, and one of these stop-nuts is provided with a sleeve 127, provided with marginal graduations coöperating with graduations on a cylindrical enlargement 128 of the corresponding section of link 124. The screw-threads and markings or graduations are so 75 proportioned as to indicate the fractional movements referred to.

To briefly summarize the action of the mold-blade and the devices connected therewith for adjusting the width of the mold-cavity to 80 correspond with that of the body of the type to be cast it may be stated that simultaneously with the shifting of the die-case to bring any of its several lines of matrix-blocks into alinement with the plunger the normal wedge 85 is correspondingly shifted, thereby adjusting the position of the stop-rod 116, so that as the mold-blade is retracted after ejecting a type it will be arrested in position to form a mold-cavity of a width exactly corresponding with 90 the width of the characters represented by the lines of matrix-blocks, hence corresponding in width to the normal dimensions of the selected matrix or character.

Abnormal adjustments of the mold for effecting justification.—Having indicated how the width of the mold-cavity is varied to correspond with variations in the widths of the types to be formed, it is next in order to explain the mechanism whereby these normal 100 adjustments may be automatically varied, and in this connection it is proper to observe that the present machine is so organized that the variations will be produced in the case of certain of the space-types rather than in all 105 of the types composing a line, although it is obvious any or all the types may be varied in the same way, if desired. The justifying mechanism is best shown as to details in Figs. 2, 7, 42, and 43 to 51, inclusive.

The plate 120, on which the normal wedge 112 reciprocates, is movably supported in guides 129, attached to the frame of the machine and is connected by a link 130 to a frame 131, which latter is supported at one 115 end upon a vertical pivot-pin 132, its opposite end being provided with a segmental flange 133, received in a guide 134 on the frame. This frame 131 stands normally substantially parallel with the guides of normal wedge 112 120 and at right angles with the direction of movement of plate 120 in its guides 129. Hence any movement of said frame 131 upon its pivot will produce a corresponding variation in the position of the normal wedge, and consequently of the stop-rod 116 controlled thereby. Reciprocating in guides on the upper portion of frame 131 is a slide 135, which is connected through yielding extension-link 136, Figs. 2 and 4, with the upper end of a lever 137, driven by a cam 138, Fig. 155, on the rear section of the main driving-shaft. As in the case of the normal wedge 112 this slide 135 is given a full reciprocation in its guides

during each complete rotation of the main driving-shaft, and its actuating-cam is of a form to hold the slide stationary at each extreme of its movement in opposite directions during successive intervals in the rotation of the main shaft—that is to say, the movements from the normal or starting point to the adjusting position are performed quickly, and the parts are held at rest after the mold has been adjusted and while the casting is being effected, after which they are quickly returned to the starting-point and there held preliminary to being again called into action. The pivoted frame 131 is furnished with a longitudinal slot or opening 139, and beneath this opening is mounted a pivoted head 140, carrying a compound slide 141, the latter composed of two sections 142 and 143, pivotally connected, the lower one fitted to reciprocate between ways formed in the pivoted head 140, and the upper one fitted to reciprocate in the guideway 139 in frame 131. The pivoted head 140 is provided with a vertical pin or pivot 144, extending through the top plate of the frame, and a transverse guiding-head 145, extending to one side of its pivot 144 parallel with and directly beneath the coincident guide or slot 139 in the frame 131 when said head 140 is in its normal or starting position. The lower section 142 of compound slide 141 is fitted to reciprocate in guides 145 of the pivoted head 140 and is provided with a hollow vertical stud 146. The upper section 143 is in like manner accurately fitted to the guiding-slot 139 in the frame 131 of the justifier and is provided with a central opening fitting the hollow vertical stud 146 on the lower section, so that the upper section is free to turn upon the lower section, the stud 146, taken in connection with the upper and lower sections of the compound slide 141, constituting a reciprocating pivotal connection between the pivoted head 140 and the pivoted frame 131. A spring 147, attached at one end to the upper section 143 of the compound slide and at its opposite end to the frame 131, serves to hold the compound slide 141 under yielding pressure at one end of the guide in pivoted head 140, with its hollow vertical stud 146 coincident with the axis of the vertical pin or pivot 144. Slide 135 is furnished near one end with an opening 148 for the reception of the head of a pin 149, said pin being vertically movable within the hollow vertical stud 146. When the slide 135 is at the right extreme of its movement or in starting position, as shown in Fig. 43, the opening 148 is coincident with the pivot 144 of the pivoted head 140, so that the pin 149, if elevated, will enter said opening 148, and thus connect the compound slide 141 with slide 135, in which case the former will partake of the reciprocating movements of the latter. For a purpose to be hereinafter explained slide 135 is provided with means for locking or retaining the pin 149 in elevated position after the reciprocating movements of the slide have been

begun and until they are terminated and the slide brought back to the starting position, Fig. 43. The means referred to include a spring-pressed latch 150, mounted upon the slide 135 and arranged to project slightly within the opening 148 and to enter a notch 151 in the head of pin 149. A pin or shoulder 152 on frame 131 is arranged to engage the latch 150 as it returns to the starting-point and serves to hold said latch withdrawn from opening 148 and out of engagement with the pin 149. When, however, slide 135 begins its movement to the left, Figs. 42 and 43, and the latch is thus carried away from pin 152, the former is permitted to enter the opening 148 and remain projecting therein until by the return movement of the slide it is again forced back by contact with pin 152. If, therefore, pin 149 is projected into opening 148 and held there during so much of the movement of slide 135 as effects the withdrawal of the latch from pin 152, said latch will engage pin 149 and hold it in position during the excursion of the slide, releasing the pin 149 and allowing it to drop as soon as the latch again makes contact with pin 152 and is withdrawn thereby from engagement with pin 149. When the parts are in normal or starting position, the guide 139 in frame 131 and the guide 145 in pivoted head 140 stand in parallel planes, so that if the compound slide 141 was reciprocated no lateral motion would be communicated to frame 131. Hence no change would be made in the position of the normal justifying-wedge 112, and its action upon the stop-rod 116 would not be effected. If, however, the pivoted head 140 is turned so that its guide 145 shall stand at an angle to the guide 139 in frame 131 and the compound slide 141 is given a reciprocating movement, (as when its pin 149 is elevated into the opening 148 in slide 135,) the lower section 142 of compound slide 141, riding in the guiding-head 145, will be compelled to follow the direction of said guide and, acting through its pivotal connection with the upper section 143, which latter is at the same time traversing in the guide 139 of frame 131, will cause frame 131 to oscillate upon its pivot 132. The degree of lateral movement thus communicated to frame 131 will be determined by the angular position of guiding-head 145, and the resultant action will be to shift the supporting-plate 120 of the normal wedge 112, and thereby vary the position of the stop-rod 116 without, however, effecting its connection with the normal wedge 112 or the control which the latter exercises upon the adjustment of said stop-rod 116. The effect of these adjustments upon the normal wedge and its supporting-plate is indicated by dotted lines in Fig. 46, the full lines indicating normal positions of the parts, while the dotted lines indicate the movements produced when the guide-head 145 is set at an angle and the compound slide 141 is reciprocated.

By virtue of the described arrangement of

parts it becomes possible to effect variations in the width of the mold-cavity, and incidentally of the type-bodies, over and above the normal variations corresponding with differences in the width of characters, which variations may properly be designated as "abnormal," as they are superadded or imposed upon the normal variations as produced by the action of the normal wedge. It will further be observed that the degree of these abnormal adjustments or variations are determined and controlled by the adjustment of the guiding-head 145, and that they are made effective only when the compound slide 141 is connected to its driving mechanism, in this case slide 135, as by the projecting of pin 149 into operative engagement with said slide. Hence it becomes possible to impose these abnormal adjustments upon all or any predetermined number of types to be made. According to the special organization of the present machine the degree of abnormal adjustment is determined for each line and is made operative upon certain of the types only—to wit, the space-types—which is accomplished by setting the guiding-head 145 at the proper angle preliminary to the formation of the types which are to form the line and connecting the compound slide 141 with its driver (the slide 135) by elevating the pin 149 each time one of the selected type or a type-space is to be formed. The mechanism for automatically effecting the adjustment of pivoted head 140 to set its guiding-head 145 at the desired angle will now be described.

To the vertical pin or pivot 144 is secured an arm 153, carrying a worm-segment 154, the latter being engaged by a worm 155, attached to a shaft 156, which latter is mounted in bearings on the frame in rear of the justifier-frame 131. (See Figs. 4, 7, 44, 45, 46, 65, and 66.) The worm-segment 154 is detachably secured to the arm 153 and is provided with a means for adjusting it toward the worm to compensate for wear. To the shaft 156 is secured a ratchet-wheel 157, the latter furnished with a shoulder 158 for engaging a stop 159, and a spring 160 is connected to this ratchet-wheel 157, the opposite end of the spring being secured to a fixed plate 161. The spring 160 is so applied that its force is exerted in a direction to hold the shoulder 158 in engagement with the stop 159 and to bring the ratchet-wheel back to this position when it shall have been removed therefrom and released. When shoulder 158 is in contact with stop 159, the worm-wheel is in position to hold guiding-head 145 parallel with the guide 139 in frame 131, and the only movement permitted to the worm is in a direction to swing head 140 rearwardly. (Indicated by dotted lines in Figs. 146, 147, and 148.) Consequently the abnormal adjustments effected in this machine will be in a direction to increase the width of the type-bodies over and above their normal dimensions. Upon shaft 156 is pivotally supported a lever 162, provided with a pawl

163 at its lower end for engagement with the teeth of ratchet-wheel 157 and having a gear-segment 164 on its upper portion. 70 The gear-segment 164 engages a rack 165, Figs. 7, 44, and 45, attached to rod 73. This rod 73, it will be remembered, is attached to and reciprocates with the slide 66, which controls the movement of the die-case in its 75 supporting-frame. Hence the motion communicated to the pawl 163 and through the latter to the ratchet-wheel 157 and its connections will be proportional to the rearward movement of slide 66. In other words, the 80 excursion of the pawl at each rotation of the driving-shaft will be determined by the movement of slide 66, which latter movement is subject to control by the stop-pins. The maximum movement of pawl 163 during any 85 single rotation of the main driving-shaft will be in exact proportion to the maximum throw of the die-case in its supporting-frame, equal to the movement of slide 66 from the starting-point to the fixed stop-pin 58, while the 90 minimum throw will correspond to the distance traversed by slide 66 in moving from the starting-point to the first of the series of stop-pins 58. Hence between these extremes there are ten intermediate degrees of movement, as determined by the intermediate stop-pins 58 of the series. The desired adjustment of the pivoted head 140 is effected while the pump is out of action, and it may require for this purpose one or more complete rotations of the main drive-shaft. For example, if the maximum movement of the pawl 163 when in engagement with its ratchet-wheel 157 is sufficient to turn the pivoted head 140 to the desired angle this result will be accomplished by allowing slide 66 to make a full stroke, the ratchet-wheel being thereafter held in adjusted position by a holding-pawl 166. After this adjustment is effected the pawl 163 is thrown out of gear with its ratchet-wheel, so that subsequent reciprocations of slide 66 during the formation of type for that line will be inoperative to effect the position of the guiding-head 145. Should the maximum movement of slide 66 be more than 105 enough to effect the desired adjustment of guide-head 145, that one of the stop-pins 58 will be utilized which by limiting the movement of slide 66 will arrest said slide at an intermediate point and produce a movement 110 of the pawl corresponding to the adjustment desired; but in the event the movement required is in excess of that produced during a complete reciprocation of slide 66 two or more reciprocations of slide 66, as controlled and 115 regulated by the stop-pins, may be employed. For example, if the adjustment effected by a complete reciprocation of slide 66 produces such a movement of guiding-head 45 as will result in the withdrawal of the mold-blade 120 twelve one-thousandths of an inch, each stop-pin representing one one-thousandth of an inch, and it is desired to add to each of the space-types, say, twenty-six one-thousandths

of an inch, the pawl 163 will be held in engagement with its ratchet-wheel 157 during two complete reciprocations of slide 66, (equivalent to twenty-four one-thousandths of an 5 inch,) after which the second stop-pin 58, controlling the movement of said slide 66, will be elevated to arrest the movement of the slide, and thus add two one-thousandths of an inch to the adjustment previously effected. After 10 the types comprising a line have been cast and another line is to be formed it is required that the justifying mechanism should be returned to zero, which position it occupies when stop 159 is in engagement with shoulder 158. To accomplish this result, the holding-pawl 166, Fig. 51, is pivotally supported and provided with actuating devices whereby it can be withdrawn from the teeth of the ratchet-wheel, whereupon the latter 15 will be quickly returned by its spring until arrested by the contact of shoulder 158 with stop 159.

It will be noticed that the adjustments of the justifying mechanism are controlled as to 25 extent of adjustment by the stop-pins 58, that the application of the justifying mechanism in the formation of any given type is controlled by pin 149, and that the release and return of the adjusting devices of the 30 justifying mechanism are effected by the movement of holding-pawl 166.

The pump and melting-pot.—The details of the melting-pot, pump, and nozzle, and their operating mechanism are best shown in Figs. 35 8 and 54 to 76, inclusive. The principal function and operation of this mechanism is to supply the molten metal to the mold after the latter has been set or adjusted and while the matrix-block is held firmly in position to close 40 the upper end of the mold-cavity, as represented in Fig. 32. The melting-pot 167 is pivotally supported upon trunnions 168, which are received in bearing-blocks 169, Fig. 70. These bearing-blocks 169 are each 45 provided with a vertical web 170, which is received between supporting-flanges 171 on the casing 172. The bearing-blocks 169 rest upon the upper faces of flanges 171 and are held 50 against lateral displacement by their webs 170, fitting between said flanges 171, while at the same time the bearing-blocks are capable 55 of horizontal motion to accommodate the position of the melting-pot with reference to the nozzle-seat as the parts become heated and expand. The casing 172, provided with a lid 173 and a flue 174 for the escape of gases, is furnished with a base 175, received within guideways on a base-frame 176, Figs. 60 and 61, the latter being detachably secured to the 60 right side of the main frame 12. An adjusting-screw 177, collared in the outer end of the base-frame 176 and engaging a nut 178, attached to the base 175, serves to effect a horizontal adjustment of the casing 172 with reference to the nozzle-seat. A burner 179, provided with a suitable controlling-valve, is arranged to project within the casing beneath

the melting-pot for heating the latter and maintaining the metal in a molten condition. The melting-pot is provided with an arm or 70 projection 180, containing the passage for the molten metal and terminating in an upright nozzle 181, whose extremity is made conical to accurately fit and become seated within the conical aperture in the nozzle-seat, Figs. 7, 75 8, and 32. Within the melting-pot is detachably secured the pump-cylinder 182, Fig. 59, the same comprising a vertical cylinder provided with one or more immersed supply-ports 183 and a tubular extension 184, communicating with the end of the passage in arm 180. A plunger 185 is arranged to reciprocate within the cylinder 182, its upper end being connected by a link to one arm of 80 a lever 186, the latter supported in bearings on the main frame and having its other arm connected, through a sectional elastic extension-link 187, with a bell-crank lever 188, supported on a shaft 189, mounted in bearings 85 on the opposite side of the frame. The movements of the plunger 185 are transmitted through this bell-crank lever 188, as will presently appear. In order to retain the metal 90 in a molten condition in arm 180 of the melting-pot, a gas-pipe 190, provided with jet-95 openings, is attached to the melting-pot and extends longitudinally of and beneath said arm. To the outer end of arm 180 is pivotally connected one end of a link 191, whose lower end is pivoted to a bell-crank lever 192, 100 Figs. 54 and 55, the other arm of said bell-crank lever being pivoted to a cam-rod 193, whose slotted head 194 embraces the left section of the main driving-shaft 13 and is provided with a pin engaging a cam 195, Fig. 105 149. The cam-rod 193 is formed in sections, with an interposed spring 196, through which motion is transmitted in a direction to tilt the melting-pot on its trunnions and bring the nozzle up within the nozzle-seat, so as to 110 form a tight joint at this point. Although this vertical movement of the nozzle takes place during each rotation of the main driving-shaft after the mold has been adjusted and is ready to receive the metal, no metal is 115 projected from the nozzle or into the mold until plunger 185 is depressed to force a stream of molten metal from the cylinder out through the nozzle. The pump is brought into action 120 only when a type is to be cast; but as the present machine is organized it becomes desirable at times that the pump should be automatically thrown or locked out of action—as, for example, when the justifying mechanism is being set preliminary to the formation of 125 a line. Hence provision is made for suspending the action of the pump or the flow of the metal to the mold, while the main driving-shaft continues in motion for a longer or shorter period, as desired. Supported loosely 130 on shaft 189 is a second bell-crank lever 197, whose upper arm stands normally parallel with the horizontal arm of bell-crank lever 188, while the other arm of said lever 197 car-

ries a pin in engagement with a cam 198. (See Figs. 55 and 147.) The groove in cam 198 is for the most part concentric with its axis, so that the lever 197 will be held stationary during the greater part of the rotation of the main driving-shaft and will be reciprocated during the balance of its rotation, the motion being so timed as to operate the pump when the nozzle has been seated.

10 The inner or horizontal arms of the two levers 188 and 197 are furnished with coincident apertures 199, adapted to receive a connecting-pin 200, so that when said pin is thrust through both apertures 199 the driving-lever 197 will be locked to the pump-lever 188, and the motions derived from the cam 198 will be transmitted to the plunger of the pump. Pin 200 stands horizontally and is provided with a vertical cylindrical shank supported loosely in a horizontally-reciprocating block 201, and the end of said pin 200 rests normally within the aperture 199 in the lever 188, so that lever 197 is at such time free to reciprocate without communicating motion to the plunger of the pump. When, however, it is desired that the pump should operate, block 201 is moved in a direction to cause the end of pin 200 to enter the aperture in the driving-lever 197, which movement is effected while 25 the pin on lever 197 is riding in the concentric portion of its cam-groove. The stem or shank of pin 200 being free to reciprocate in its supporting-block 201 partakes of the movement of the levers so long as it is engaged by 30 both; but when withdrawn from lever 197 it occupies the position represented in Fig. 74. A reciprocating movement is communicated to block 201 in a direction to cause the alternate engagement and disengagement of pin 200 with lever 197, said movements being derived from the mold-blade cam 108. This is effected by securing lever 105 of the mold-blade-actuating mechanism to a shaft 202, mounted in bearings on the frame and provided with a depending arm 203, Fig. 8, whose lower end is connected to block 201 by an elastic compression-link 204. The spring 206 of compression-link 204 is so arranged that it transmits the movement of arm 203 in a 45 direction to cause the engagement of pin 200 with the driving-lever 197, at the same time permitting block 201, carrying the connecting-pin 200, to be arrested during the forward movement of arm 203. A stop-pin 207 is arranged so that it can be projected into the path traversed by block 201, and thus arrest the movement of said block before the pin 200 enters the driving-lever 197. When 50 the casting of types is being performed, block 201 makes a complete reciprocation and effects the engagement of driving-lever 197 with the pump-lever 188 at the proper time to cause the pump to operate and force the molten metal into the mold, after which the pin 200 is withdrawn until the next succeeding type 55 is to be formed, when the operation is repeated. When it becomes desirable to suspend

the operation of the pump, it is only necessary to project stop-pin 207, and thus arrest the movement of block 201 and prevent the engagement of its pin 200 during the movement of lever 197.

It is important that the nozzle should accurately fit its seat before the pump is operated to inject the molten metal into the mold. Hence it becomes a matter of no little importance to prevent the dropping of scraps, dirt, &c., upon the nozzle when withdrawn from its seat. This result is attained in a satisfactory manner by causing the slide containing 80 said passage to move to one side while the nozzle is still occupying its seat, whereby the jet or block of metal in passage 88 is cut off from the type above and the nozzle beneath, and the orifice through which the nozzle 85 delivers the metal is closed before the nozzle is withdrawn from its seat, thus preventing the discharge of dirt, &c., upon the nozzle.

Up to this point we have considered those elements of the machine which operate to 90 form the types, including the centering of the selected matrix, the formation of a mold suited to the character of the matrix, and the injecting of molten metal into the mold-cavity to complete the formation of a type. We 95 will now proceed to describe the mechanism for receiving the completed types and delivering them one at a time to the galley mechanism, by which they are assembled in lines and the lines in columns.

Type receiving and transferring mechanism.—The injection of the molten metal into the mold may be taken as marking the completion of a single type, and when this has been accomplished the die-case is elevated 105 and returned to starting position, the front wall 83 of the mold-cavity is moved to one side, thus opening the front of the mold and incidentally severing the jet from the type, and the mold-blade 96 is advanced or moved 110 forward, so as to eject the finished type from the mold. As the type leaves the mold it is received in the type-carrier 208, Figs. 1, 8, 9, and 77, which latter reciprocates in line with slide 84, carrying the front wall 83 of mold, 115 and is provided with devices or means for receiving and retaining the type in upright position while being translated from the mold to the galley mechanism. This type-carrier 208 is mounted upon a slide 217, Figs. 8 and 31, reciprocating between guides 218 beneath slide 50. A cam 218, Fig. 148, on the left section of main drive-shaft operates through lever 220 and head 221 to reciprocate slide 217 at the proper time. The type-carrier 208 is furnished with an open slot or way for the reception and passage of the type, one of the walls of said way being furnished with an elastic retainer 222, Figs. 8, 115, and 117, which latter is provided with a stem 223, surrounded by a spring 224, operating to hold the retainer projected slightly beyond the wall of the channel or way, but permitting said retainer to yield when a type is forced 120 125 130

into the channel, and the outer face of said retainer is slightly beveled, as indicated in Fig. 115, to facilitate the entrance of the type. When the slide 84 is moved to uncover the front of the mold, the type-carrier is immediately moved into position in front of the mold with its way or channel in line with mold-blade 96, so that when the latter is advanced the completed type will be delivered within the way or channel of the carrier. The carrier bearing the type is quickly withdrawn to the position indicated in Fig. 9 and held for a moment opposite ejector-blade 210 and in line with the receiving type-channel 209 of the galley mechanism, so that when the ejector 210 is advanced it will drive the type through the channel or way in the type-carrier and deposit it in the type-channel 209, as shown in Fig. 77. The ejector 210 is attached to a slide 225, mounted to reciprocate horizontally in guides attached to the frame and driven by lever 226, pivotally supported on the frame and connected by link 227, Fig. 8, to an arm 228 on sleeve 342, the latter turning loosely on shaft 202 and provided with an arm 343, to which one end of cam-rod 344 is attached. The opposite end of cam-rod 344 is furnished with a slotted head 345, embracing the rear section of drive-shaft and carries a pin-engaging cam 346, Fig. 154, on said shaft.

Galley mechanism.—Before entering upon a detailed description of the various parts comprising this mechanism it may be of advantage to first consider the principal elements and their special uses and functions.

The types are delivered one at a time by the carrier 208 and pusher or ejector 210 into a type-channel 209, where the line is assembled. The outer portion of this type-channel extends across the end of a galley 211 and is separated therefrom by a vertically-movable blade or rule 212, forming one wall of said channel, the opposite wall being formed by a movable head or line-transferrer 213. A type-sustaining-blade 241 is arranged to traverse in the type-channel 209, the entering type forcing said blade back, and after the removal of the completed line said blade is turned automatically and positively to normal position at or near the entering end of the type-channel. When a full line of type has been assembled in the line-channel 209, a line-carrier 215 is projected beyond the last type of the line, and the whole line is drawn along the type-channel until brought opposite the entrance to the galley. The rule 212 is then elevated, and the line-transferrer 213 is advanced in a direction to shift the line of type into the galley, after which rule 212 partly descends a short distance to prevent the type from falling or being carried back into the line-channel, the head 213 is withdrawn, the rule 212 completes its downward movement, and the operations are repeated for the next succeeding line. Should the line from any cause be too long or too short, an

automatic stop 216 is provided for stopping the machine, thus giving warning to the attendant and preventing damage.

Turning now to the specific embodiment illustrated in the drawings, it will be seen that the entering end of type-channel 209 is formed by a bar 229, Fig. 81, and two blocks 230 and 231, forming opposite sides. These blocks 230 and 231 are grooved longitudinally along their proximate faces and each is furnished with a series of holes or apertures for the reception of spring-pressed holding-dogs or type-supporting members 232, Figs. 86 to 92, inclusive. Each dog 232 is provided with a limiting-screw 233, and its outer or engaging face is slightly inclined, as shown in Fig. 86, to facilitate the passage of the types and assist in retaining them in upright position, and the vertical joints between contiguous dogs are interrupted by providing the dogs with overlapping sections, whereby all danger of the corners of the type catching so as to impede their passage or disturb their proper position is avoided. The dogs located at opposite ends of the blocks are also provided with rearwardly-projecting shoulders 234, working in recesses in the blocks. It may here be remarked that the galley mechanism, with the exception of the type carrier and ejector heretofore described, is all mounted upon a bed plate or frame 235, Fig. 94, detachably secured to the front side of the main frame 12, and that the bar 229, forming the bottom of the type way or channel, is attached at 236 to the left end of said galley 235.

The head 213, Fig. 98, is arranged at the front end of block 230 and constitutes a portion of one wall of the type way or channel. It comprises a vertical web or plate having an overhanging portion or flange 237, whose lower edge is in line with the upper edge of bar 229, and said head is adapted to move transversely over the latter. In the upper face of said head or line-transferrer 213 is formed a dovetailed groove 238, in which is received the dovetail portion of a type-sustaining slide 239, said slide being provided with a vertical flange or extension 240, extending into the type way or channel and carrying a projection or type-sustaining blade 241 at its rear end or that end nearest the type-carrier. The reduced end or projection 241, carried by this slide 239, serves as a sustainer for the types as they are forced from between the rearmost holding-dogs 232, an adjustable friction-spring 242, working against the bottom of the dovetail groove 238, serving to exert the required frictional resistance to the movement of said slide to sustain the line of types and at the same time to retreat as the types are advanced by the line-carrier 215. Head 213 is attached to two parallel rods 243, mounted to reciprocate in bearings in the frame and provided with a cross-head 244, through which motion is communicated to said head in a direction transverse to the type-channel.

- The outer end of block 231 constitutes one side of the mouth or entrance to the galley, the opposite side of said entrance being formed by a block 245, detachably secured to a slide 246, movable in ways 247 in the face of galley-frame 235. The slide 246 is provided with a detachable end section 248, fitting within the groove between ways 247 to provide a level floor over which the type may 5 pass into the galley, so that when slide 246 is adjusted to receive longer or shorter lines of types other sections, like 248, but of a length adapted to fill the interval, may be substituted.
- 10 The vertically-movable rule or blade 212, forming the wall of the type-channel opposite head 213 and closing the entrance to the galley, is attached at one end to a vertical rack-bar 249, supported in guides in the frame and 15 engaged by a segmental gear 250, Figs. 82 and 127. As before described, this rule or blade 212 occupies its lowermost position (indicated in Fig. 85) when the line of type 20 emerges from between the holding-dogs 232 into that part of the type-channel extending 25 between said blade and the head 213; but as soon as the completed line of types is brought opposite the galley-entrance, pushing slide 239 before it, blade 212 is elevated to the position 30 shown in Fig. 84 and head 213 is moved to the right, thereby shoving the line of types beneath blade 212 into the galley-entrance, after which blade 212 makes a partial descent in rear or to the left of the line of type to prevent 35 them from falling or becoming disarranged, the head 213 is retracted, and blade 212 completes its downward movement and again occupies the position indicated in Fig. 85.
- 40 The principal object in employing line-carrier 215 is to enable the transfer of the completed line from the receiving way or channel 209 to the galley without interrupting the formation and assembling of types for the 45 next succeeding lines. It is furnished with fingers 251, which at the completion of a line are projected behind the last type of the line, then moved longitudinally of the type way or channel 209 up to a point opposite the rear 50 wall of the entrance to the galley, after which they are moved to the left and carried back in a different vertical plane, so as to escape the types supported between holding-dogs 232, and are finally brought to rest in position 55 to enter behind and engage the next completed line of types. The fingers 251, Fig. 106, are pivotally supported on plates 252, secured to the rear end of a sliding rack-bar 253, Fig. 100. Said rack-bar is supported to 60 reciprocate parallel with the type way or channel in guides formed in a plate or frame 254, Figs. 83, 84, and 85, the latter mounted in ways 255 formed in extensions 256 of galley-frame 235. The ways 255 are at right angles 65 to the guides in which rack-bar 255 reciprocates, whence the movements of frame 254 are in a direction to carry the rack-bar and fingers transversely of the type-channel for bringing the ends of fingers 251 into or out of engagement with the type. The necessary 70 reciprocating movements of frame 254 are communicated through gear-segments 257, engaging racks 258 on the under side of said frame, while the longitudinal movements of the rack-bar 253, carrying the fingers, are in 75 like manner produced by a gear-segment 259 engaging said rack-bar. By properly timing the movements of the gear-segments 257 and 259 the fingers 251 will be carried behind the last type of the completed line and by a longitudinal movement of said rack-bar be made to shift the line of types into position in front of the galley. Then by a movement of frame 254 withdraw the fingers from the type-channel and hold them withdrawn while they are 80 being returned in position to engage the next succeeding line of types when completed. As the line of types is drawn forward opposite the galley, slide 239, which by its projecting end or type-supporting blade 241 supports the 85 front end of the line, is forced longitudinally beyond the front wall of the galley-entrance and it becomes necessary to return said slide and leave it in position to receive the next succeeding line of types. The mechanism 90 for returning said slide is mounted upon frame 254. It includes a rack-bar 260, reciprocating longitudinally of rack-bar 253 and driven from the latter through gears 261, supported on a vertical shaft 262, secured to frame 254. 95 The lower and smaller gear 261 engages a rack 263, formed on the side of rack-bar 253, while the upper and larger gear 261 engages the teeth formed on rack-bar 260, the object being to effect an increased motion of rack-bar 260 as compared with that of its driver 100 253. Upon slide 239 is secured a block 264, and to rack 260 is secured a block 265, provided with an overhanging portion carrying a dog 266, Fig. 124, held projected by an adjustable spring. When the parts are in position represented in Figs. 9, 81, and 85, the dog 266 occupies a position to one side of block 264, so that the latter is free to pass the pawl as it is driven back by the type. Frame 105 254 being moved to bring fingers 251 behind the last type of the line, the movement of rack-bar 253 to cause the fingers to transfer the line opposite the galley-entrance will, through gears 261, cause a further traverse in 110 the same direction of the dog 266, bringing the latter beyond block 264. After the line has been transferred to the galley and the head 213 has returned to position frame 254 moves to the left until dog 266 is brought in alignment with block 264 on slide 239, and while the parts occupy these relative positions rack-bar 253 is moved rearward or toward the type-carrier, causing dog 266 to engage block 264 115 and carry slide 239 back to normal position, 120 after which frame 254 is moved to the right sufficiently to carry dog 266 out of alignment with block 264 without, however, causing fingers 251 to enter the type-channel.

Block 245, constituting the adjustable front wall of the galley-entrance, is furnished with a horizontally-movable section 267, Figs. 84, 85, and 108 to 113, inclusive, forming part of the automatic stop mechanism for arresting the motion of the machine in case the line fed to the galley is either too long or too short. The movable section or trip-block 267 is fitted to guides in the rear face of block 245 and is provided with a recess 268, in which is received the head of a lever 269, the latter pivotally supported upon a pin 270, extending longitudinally of the adjustable supporting-slide 246. The lower end of lever 269 is engaged by a wide lever 271, pivoted in the frame, and through this last-named lever the movable section 267 operates upon the belt-shifter, as hereinafter explained. The portion of lever 271 which engages lever 269 is made sufficiently wide to accommodate various adjustments of block 245. The end of movable section 267, facing type-channel 209, is provided with a horizontal groove or recess 272, adapted to receive the reduced portion or projection 241 on the vertical flange 240 of slide 239, and said movable section 267 rests normally with its grooved end just to one side of the rule or blade 212 when in its lowermost position, as shown in Fig. 85. If the line of types drawn to position in front of the galley-entrance by line-carrier 215 is of normal or standard length, the projection 241 of supporting-slide 239 will be brought in line with the inner or rear face of movable section 267, as shown in Fig. 108, so that when slide 213 is moved to push the line into the galley projection 241 will enter the groove or recess 272 and the line will be advanced without changing the position of the movable section 267. If the line is above the normal or standard length, one or more of the types will be carried opposite the grooved end 272 of movable section 267, (see Fig. 109,) so that when head 213 is moved in a direction to push the line into the galley-entrance the intervening type or types will cause the movable section 267 to be forced back, thereby setting the automatic stop mechanism in action. The same effect will be produced if the line is too short, as under such circumstances the wider portion of vertical flange 240 will stand in front of the movable section 267, (see Fig. 110,) forcing the latter back as head 213 advances.

The galley 211, onto which successive lines of types are delivered as they emerge from between the side walls of the galley-entrance, comprises a detachable frame open at one end and provided with a flat bottom 350 and raised margins 351. The open end of the galley rests upon the ribs 352 of galley-frame 235, while the outer or right end is supported upon cross bar 353, Fig. 102, adjustably supported upon rods 354, attached to galley-frame. The cross-bar 353 is provided with a grooved way to receive adjustable corner-blocks 355, Figs. 1, 2, and 101, for sustaining the right end of galley in position, the left

end of galley being held between a stop 356 on block 231 and an adjustable block 357, seated in a groove in the galley-frame. The bottom 350 of the galley is flush with the surface of slide 246 and its detachable section 248, forming the bottom of the galley-entrance, so that no obstruction will be presented to the movement of the type onto the galley. To accommodate the galley to lines of different lengths, it is provided with a removable and adjustable bar 358, one end of which is provided with a vertical rib 359, engaging a groove in adjustable block 245 for maintaining the inner face of said bar 358 in alignment with the inner face of block 245, while the opposite end of said bar 358 is attached to a block 360, adapted to be fastened in adjusted position upon cross-bar 353.

The various movements given to the several parts of the galley mechanism are derived from a counter-shaft 273, arranged at the right-hand side of the machine, as indicated in Figs. 1 and 5. This counter-shaft 273 receives motion from a worm 274 on the left section of main driving-shaft, Figs. 2 and 4, engaging a worm-wheel 275 on a shaft 276, the latter connected through beveled gears 277 with the rear end of shaft 273, whereby the speed of said counter-shaft 273 is very much reduced. A cam 278, Fig. 159, acting on lever 279, the latter connected by link 280 with segmental gear 250; Figs. 3, 127, and 178, controls the vertical movements of the rule or blade 212. The gear-segments 257, which operate frame 254, carrying the line-carrier 215 and type-sustainer 214, are mounted upon a shaft, Fig. 127, and said shaft is provided with an arm 282, to which is attached one end of a rod 283, Fig. 128, provided with a compression-spring 284 and driven by the cam 285, Fig. 160, on the counter-shaft 273. The longitudinal reciprocations of the line-carrier 215 are produced by a cam 286, Figs. 5 and 153, acting upon lever 287, the latter connected by a link 288 to an arm on shaft 289, extending longitudinally beneath the galley and carrying gear-segment 259, engaging rack-bar 253, to which latter fingers 251 are attached. The reciprocating movements of head 213 are derived from the cam 290, Fig. 152, on counter-shaft 273, said cam acting on a lever 291, whose upper end, Fig. 85, is connected to cross-head 244 through a yielding connection formed by spring 292 and rod 293, the latter pivotally connected at one end to lever 291 and having its opposite end loosely fitted within a sleeve pivoted to cross-head 244.

It will be remembered that the movable section or trip-block 267 of the automatic stop mechanism when displaced either by the engagement of the type-sustaining blade 214 or by the types themselves acts through its lever 269 upon lever 271. This lever 271 is connected by a bar 294 to a lever 295, Fig. 128, attached to a shaft 296, the latter provided with a handle 297. The other arm of lever 295 rides upon a segment 298, carried by a

shaft 299, which latter controls the belt-shifter 300 through an arm 301. The segment 298 is provided with a shoulder 302, which is engaged by lever 295 when shaft 299 is turned 5 to a position to carry the belt upon the fast pulley, said lever 295 being held in position to engage shoulder 302 by spring 303, Figs. 85 and 127, engage bar 294, so that when shaft 299 is turned by its hand-lever 301 or otherwise to start the machine the driving-shaft is continued in motion so long as lever 295 retains its position behind shoulder 302 of segment 298. When, however, lever 295 is rocked, either through movable section 267 15 of the automatic stop mechanism or by the hand-lever, a spring 305, acting upon the belt-shifter, will transfer the latter from the fast to the loose pulley, and thus arrest the driving-shaft.

As the galley mechanism is brought into action only upon the completion of a line of types, it is desirable that means should be provided for controlling the time and duration of its movements. A special form of mechanism for this purpose is illustrated in Figs. 129 to 137, inclusive. The worm-wheel 275, receiving motion from the worm on the left section of the main driving-shaft, is formed upon or secured to a sleeve 306, mounted to turn loosely upon shaft 276, through which latter motion is communicated to counter-shaft 273 of the galley mechanism. This sleeve 306 is provided with ratchet-teeth 307, while shaft 276 has secured to it a head 308, carrying a pivoted pawl 309, whose teeth 310 are adapted to engage the ratchet-teeth 307 for connecting the continuously-rotating sleeve 306 with shaft 276, so as to cause them to rotate together and actuate the galley mechanism. It is important that shaft 276 should always start from the same position. Hence means have been provided for controlling the engagement of pawl 309 with ratchet-teeth 307 and for effecting its disengagement and the stopping of shaft 276 at the end of each complete movement of the galley mechanism. A spring 311 is arranged to bear upon the toothed end of pawl 309, acting thereon in a direction to effect the engagement of said pawl with the ratchet-teeth and to maintain such engagement. The pawl itself is segmental in form, and its tailpiece is provided with a shoulder 312, adapted to be engaged by one arm of a lever 313. A spring 314 is arranged to hold lever 313 in engagement with the outer face of pawl 309 and in position to engage shoulder 311 thereon, so that pawl 309, having once been caused to engage ratchet-teeth 307 on sleeve 306, thereby starting shaft 276 in motion, the latter will continue to revolve until shoulder 312 on pawl 309 engages the point of lever 313, when the pawl will be swung on its pivot to cause its withdrawal from the ratchet-teeth, and shaft 276 will be arrested and held by the contact of lever 313 with the shoulder on the pawl. In order to start the galley mechan-

ism, it is only necessary to oscillate lever 313 upon its pivot, so as to release pawl 309, whereupon motion will be at once transmitted 70 through the pawl to shaft 274 and the galley mechanism; but it is desirable that the lever 313, after having effected the engagement of the pawl with the ratchet-teeth, should be at once placed in position to arrest the movement of shaft 276 and insure the stopping of said shaft at the completion of one revolution. With this end in view a trigger 315 is employed. This trigger is pivotally attached at its lower end to a vertical slide 316 and is 80 provided near its upper end with an incline 317 for engagement with a fixed pin 318 and with a shoulder 319 for engagement with lever 313. A spring 320 is arranged to hold the trigger 315 normally in elevated position, 85 as indicated by dotted lines in Fig. 130, the incline 317 riding against pin 318 to swing the trigger away from lever 313, and the shoulder 319 being elevated above said lever the latter is free to either ride upon or engage shoulder 312 on pawl 309. When it is desired to start the galley mechanism, slide 316 is drawn down and released, whereupon spring 320 will quickly elevate said slide, causing shoulder 319 to engage lever 313 and 95 withdraw it from shoulder 312 on pawl 309, thus starting the pawl and shaft 276 in motion, and the continued vertical movement of the trigger 315 will effect an engagement of its inclined portion 317 with the fixed pin 100 318, thereby swinging said trigger to one side and withdrawing its shoulder 319 from engagement with lever 313, thus liberating said lever 313 and permitting it to swing back toward pawl 309 in position to reengage shoulder 105 312, and thus arrest the galley mechanism.

Paper controller and feed.—This mechanism comprehends those parts of the machine which support the perforated controlling-strip and effect its progressive movement to present successive sections in position to render operative the several devices used in connection with the pneumatic controlling system. The details of this mechanism are represented in Figs. 139, 140, and 141. In the preferred 110 form of apparatus two spools are employed, the one, 321, containing the supply and the other, 322, receiving the strip after it has passed the pneumatic devices, a single strip being utilized to govern the entire machine. 115 The paper strip passes over and is drawn flat upon a rounded cross-bar 323, and at each end of said cross-bar is arranged a pin-wheel 324. These pin-wheels are mounted upon a shaft 325, provided at one end with a ratchet-wheel 326 and at the opposite end with a pulley 327, from which latter motion is transmitted through an elastic wire belt 328 to pulley 329 on the shaft of receiving-spool 322. The advance of the paper strip is controlled 120 by the rotation of the pin-wheels 324, the spool 322 assisting and serving to take up the strip as it is advanced. The elastic belt 329 operates as a yielding driver for said spool 125 130

and compensation for variations in the diameter of the spool as the strip is wound thereon. A holding-pawl 330, mounted on the frame and engaging ratchet-wheel 326, serves 5 to prevent back motion of shaft 325, while a pawl 331, carried by an arm 332, serves to rotate or advance the shaft a determinate distance at each reciprocation of arm 332. In order to prevent overthrowing or the advance 10 movement of the ratchet beyond the point requisite for effecting the desired feed movement, a second ratchet-wheel 333, with its teeth standing in a direction the reverse of the teeth on ratchet-wheel 326, is fastened 15 to the shaft in position to be engaged by pawl 334. This pawl 334 is held by its spring 335 normally out of contact with ratchet-wheel 333, and it is thrown into engagement with said ratchet-wheel by a projection 336 20 on arm 332 engaging said pawl just before the end of the feeding stroke of arm 332, so that said pawl 334 will be thrown into engagement with its ratchet-wheel just before the feeding-pawl finishes its stroke, thus insuring 25 the stopping of the pin-wheels in the desired position. Motion is transmitted to the pawl-carrying arm 332 through a compression-link 337, pivoted at one end to said arm and at the opposite end to a lever 338. The 30 lower end of lever 338 is connected by a detachable link 339 to a lever 340, pivoted on the left side of the machine and engaging a cam 341, Fig. 150. The feeding movement of the controlling-strip is performed during a 35 portion of each revolution of the driving-shaft, and it precedes all the other mechanisms in point of time, inasmuch as through its agency the other mechanisms are controlled or set in action.

40 *The pneumatic controlling system.*—It will be remembered that the position of the die-case is controlled by the rear and left-hand series of stop-pins 58; that the amount of justification is determined by said stop-pins 58 acting in conjunction with justifier-pawl 163; that after the justifying mechanism has been 45 adjusted for the line the time for its application to the mold-blade is determined by justifier-pin 149; that the action of the pump is under the control of pin 207; that the galley mechanism is responsive to the action of slide 316, carrying the trigger 315, and that the 50 resetting of the justifying mechanism is effected by the movement of the release-pawl 166.

55 There may thus be said to be six distinct points of centers of control—first, adjusting the justifying mechanism to suit the requirements of the line of types to be formed; second, selecting the matrix or matrix-blocks 55 for each successive type and simultaneously therewith adjusting the mold to correspond with the normal dimensions of the selected type; third, effecting the abnormal adjustments of the mold by connecting the adjustable member of the mold with the previously-adjusted justifying mechanism; fourth, controlling the action of the pump; fifth, setting

the galley mechanism in action at the completion of the line of types, and, sixth, releasing or resetting the justifying mechanism 70 preliminary to the formation of the next succeeding line of type. It is obvious that these several controlling devices might be brought into action by hand or by a system of mechanism competent to operate the several controlling members at the proper time and in the proper order; but in the present machine a pneumatic system has been introduced for establishing communication between the controlling-strip and the controlling members of 80 the several mechanisms, thus rendering the machine as a whole automatic in its action and controllable in its movements by the proper arrangement and disposition of the perforations in the controlling-strip. 85

Upon reference to Figs. 140 to 144, inclusive, it will be seen that cross-bar 323, over which the controlling-strip is fed or advanced, is provided with a longitudinal series of ports or perforations 361, with each of which is connected a pipe 362. Above bar 323 is arranged a cross-head 363, mounted to reciprocate vertically in guides formed upon the uprights, to which said cross-bar is attached. A longitudinal groove or recess is formed in the upper face of cross-head 363 to receive a bar 364, the latter adjustably connected to the cross-head by bolts 365. Springs 366 are interposed between the bar and cross-head, so that when motion is communicated to the bar 90 364 in a direction to elevate the cross-head the bolt-heads will be engaged and the lifting of the bar will be positively effected, whereas when motion is communicated in the opposite direction the cross-head will be 95 subjected to the elastic pressure of the springs 366. Bar 364 is provided with rollers 367, resting in cam-grooves formed in sectors 368, the latter secured to a cross-shaft 369, provided with an arm 370, connected by a link 100 371 to the upper end of the lever 338, which actuates the paper-feed. The cam-grooves in sectors 368 are of a form adapted to elevate cross-head 363 when at one extreme of the movement communicated to them by lever 105 338—that is to say, when said lever has made its back stroke to retract driving-pawl 331 of the paper-feed preliminary to the next succeeding feed movement and to depress said cross-head and to bring it in contact with the 110 surface of the controlling-strip at about the time the driving-pawl 331 has made its complete movement in the direction to effect the feeding of the controlling-strip. Lever 338 is given a slight excess of motion over and above 115 that necessary to produce a complete reciprocation of the feed-pawl, so that after the arm 338, carrying the driving-pawl, has been arrested by the engagement of the locking-pawl 334 with its ratchet-wheel said lever 338 120 may continue to advance, (the compression-link 337 yielding,) causing a further depression of bar 364 and a compression of springs 366, whereby cross-head 363 will be held firmly 125 130 135

and elastically in contact with the controlling-strip, clamping the latter against cross-bar 323. The object of this arrangement is to release the controlling-strip during the feed 5 movement and to clamp and hold it firmly between the cross-bar 323 and movable cross-head 363 in the intervals between feeding movements. Cross-head 363 is provided with a series of ports or perforations 372, corresponding in number and registering with the ports 361 in cross-bar 323, and said ports or perforations 372 are in open communication with a passage or chamber 373, the latter communicating with a main air-supply pipe 374. 10 Communication between passage 373 and the supply-pipe 374 is made through the valve-chest 375, supported upon an extension of cross-head 363 and containing a valve 376, opening downward or toward the supply-pipe 374. A spring 377 is arranged to hold valve 376 normally in closed position or so as to prevent the admission of air to the chamber or passage 373 in cross-head 363, and an arm 378, carried by cross-shaft 369, is arranged to engage 15 the stem of valve 376, when by the oscillation of said shaft the cross-head 363 has been brought in contact with the controlling-strip, so that during the final movement of the shaft for pressing the cross-head firmly 20 down and clamping the controlling-strip valve 376 will be opened and air or gas under pressure will be admitted to chamber 373 so long as cross-head 363 remains depressed and until by the reverse movement of cross-shaft 369 arm 378 is withdrawn from contact with valve 376, when the latter will be closed 25 against its seat and the supply of air shut off. The controlling-strip is provided with a series of perforations along each edge registering 30 with the pins upon feeding-wheels 324, and what may be termed the "operating" perforations in the controlling-strip are formed in lines running transversely of the strip, and said perforations are so related to the registering 35 perforations along the edges of the strip that at the completion of each feed movement the operating perforation or perforations will be brought opposite one or more of the ports 361 and the corresponding ports 372, so that 40 each section of the controlling-strip will establish communication between one or more of the ports 361 and the opposite ports 372, the other ports of the series being closed by the interposition of the unperforated portion 45 of the controlling-strip. It will thus be seen that at each reciprocation of cross-head 363 a section of the controlling-strip will be clamped down upon cross-bar 323 and air under pressure will be admitted to the air-chamber 373 50 in said cross-head and will be transmitted through such of the ports 361 and 372 as are uncovered by the perforations contained in the controlling-strip, all the other ports remaining closed. 55 Referring now to Fig. 146, in which is represented diagrammatically the arrangement of the pneumatic system, the working of the 60 system will be made plain; but before explaining the several lines of communication therein represented it is proper to remark 70 that each stop-pin 58 is furnished with a head or piston 279, Fig. 30, working in a cylinder formed in its supporting-block, and is held normally depressed or out of operating position by a retracting-spring 380. Justifier-pin 149 is also furnished with a retracting-spring 331, Fig. 96, for holding it normally retracted, and it is furnished with a piston-head 382, working in a cylinder. Stop-pins 207 (here being two of these pins) are normally held retracted by springs 383, Figs. 74 and 75, and furnished with pistons 384. Slide 316, carrying trigger 310 for setting the gallery mechanism in motion, is held normally elevated by the spring connected to said trigger and is connected to a piston 385, Figs. 129, 130, and 131. Justifier-pawl 163 is provided with a piston 386, Fig. 7, working in a cylinder and connected to said pawl by a stem 387, a spring 388, engaging said stem, 80 serving to hold the pawl normally out of engagement with its ratchet-wheel, and the arm carrying release-pawl 166 is provided with a piston 389, Fig. 44, whose rod is connected through lever 390 and link 391 with said release-pawl, a spring 392 serving to normally hold the release-pawl in engagement with the ratchet-wheel of the justifying mechanism. 85 For convenience of reference the several ports in cross-bar 323, as represented in Fig. 146, which connect with the left series of stop-pins 58, together with said stop-pins, are supplied with numbers 2 to 11, inclusive, corresponding with the series of lines of matrix-blocks represented in Fig. 22, the final or 90 fixed stop-pin of this series being represented by the fixed pin 1, and in like manner the ports and stop-pins 58 of the rear series are lettered *a* to *k*, inclusive, corresponding with the columns of matrix-blocks as represented 95 in Fig. 22, the column marked 1 in said figure being represented by the fixed stop-pin *l*. It will be seen that each of the ports 2 to 11 100 communicates with the piston-chamber of one of the stop-pins 58 of the left-hand series 105 and that each of the ports *a* to *k*, inclusive, communicates with one of the cylinders containing stop-pins 58 of the rear series, so that 110 when a perforation in the record-strip is presented opposite one of the numbered ports 115 and at the same time another perforation is presented opposite one of the lettered ports 120 the corresponding stop-pins 58 will be elevated and the matrix-block occupying a position at the intersection of the designated 125 line and column will be brought in position above the mold. If a perforation is formed opposite one of the lettered ports and nine 130 opposite the numbered ports, the corresponding lettered stop-pin will determine the location of the matrix-block in the lettered column in the line numbered 11, the line being controlled by the fixed stop-pin. So, too, if the perforation occurs opposite one of the

numbered series of ports and no perforation is presented opposite one of the lettered ports the column will be determined by the fixed stop-pin 7, while the line will correspond with 5 the number of the stop-pin. Thus by forming one or more perforations in the record-strip in position to coincide with any one of the series of lettered or numbered ports or by forming two perforations, one corresponding 10 with a lettered port and the other with a numbered port, any one of the series of matrix-blocks, Fig. 22, may be brought into position.

General operation.—As the controlling-strip is fed to the machine in the reverse order to that in which it is prepared—that is to say, the last line and last character first—in order that the justification for the line may be provided for in advance, I will proceed 15 to explain the action of the justifying mechanism. The first thing to be done is to stop the pump and throw the justifier-pawl 163 in engagement with its ratchet-wheel and actuate it so as to set the controlling member of 20 the justifying mechanism at the proper angle. This is accomplished by forming in the controlling-strip a perforation opposite the port marked "justifier-hole," Fig. 146. This justifier-hole communicates with two pipes or 25 passages, the one, 393, leading to the cylinder of the justifier-pawl 163 and the other, 394, leading to one of the stop-pins 207 of the pump-locks, so that when air under pressure is admitted through said perforation the justifier-pawl will be thrown into engagement 30 with its ratchet-wheel and the stop-pin 207 will be projected, so as to arrest the movement of the block carrying the pin for establishing communication between the pump and 35 its driving mechanism. This condition is established during the first portion of the rotation of the main drive-shaft after the feed of the controlling-strip has been effected and the cross-head 363 brought down to clamp 40 the controlling-strip and open the inlet-valve and before the movements of the die-case are 45 begun. If the amount of justification required is equal to or exceeds that produced at one complete movement of the justifier-pawl 163, no perforation is made opposite one 50 of the lettered ports controlling the rear series of stop-pins, and in consequence the justifier-pawl will be given its full movement; but if the desired movement is less than that effected by a full reciprocation of the justifier-pawl a perforation formed opposite that one 55 of the lettered ports corresponding with the extent of movement desired will by opening communication with the stop-pin 58 of the 60 rear series limit the movement of the justifier-pawl, and thus effect a lesser degree of adjustment. Should one complete movement of the justifier-pawl be insufficient, the next succeeding section of the controlling-strip 65 will be provided with a perforation opposite the port marked "justifier-hole" and another opposite that one of the lettered se-

ries of ports calculated to effect the requisite additional movement of the justifier-pawl during the next succeeding rotation of the 70 driving-shaft. The object in suspending the action of the pump while the justifying mechanism is being set is to prevent the formation of types during the rotation or rotations of the driving-shaft required to effect said adjustment, which is necessary, because the devices which control the movements of the die-case are in this instance utilized for controlling the amount of justification, and if the action of the pump was not suspended the 80 casting operation would be performed simultaneously with the setting of the justifier. The justifying mechanism having thus been set for the line, the formation of types is proceeded with, and at each revolution of the 85 main driving-shaft one or more of the stop-pins 58 is or are elevated to locate the die-case, the mold is adjusted, the pump operated to inject molten metal into the mold, and the completed types transferred to the 90 type-carrier, and this continues until a space-type is to be formed. The port marked *a*, controlling the first of the rear series of stop-pins 58 and corresponding with the column *a* in the die-case, Fig. 22, is utilized for forming the space-type, which may be of any of the dimensions represented by the several lines 1 to 11, inclusive, in the die-case. The space-type alone receives the increase due to 95 justification. Hence when a space-type is to be formed the previously-set justifying mechanism should be connected with the mold-blade in order that the position of the latter in the mold may be properly adjusted. With this end in view the port *a*, which is always 100 opened or uncovered by a perforation in the record-strip when a space-type is to be formed, is placed in communication with the cylinder of the justifier-pin 149, as by a branch pipe or passage 395, so that the justifier-pipe will 105 be elevated to connect compound slide 141 with its actuating-slide, and thus shift the support of the normal wedge and set the mold-blade during the rotation of the main driving-shaft accompanying the formation of said 110 space-type, after which the operation of forming character-type is continued.

Between the perforation or perforations representing the last-made type of one line a perforation is formed in position to register with the port marked "galley-hole." This port is in communication with one of the stop-pins 207 and the pistons controlling release-pawl 166 and trigger 135 of the galley-starting devices, so that when a perforation is brought 115 opposite said galley-hole air under pressure is admitted to the three cylinders and operates to arrest the pump, start the galley mechanism in action for disposing of the previously-formed line of types, and release the 120 ratchet-wheel of the justifier mechanism, so that its spring may return it to normal position ready to respond to the movements indicated and produced by the next succeed-

ing justifying perforation or perforations calculated to set the justifying mechanism for the next succeeding line.

Having thus described my invention, what I claim as new is—

1. In a type-making machine such as described, the combination of the following elements; to wit, a series of matrices; a mold provided with an adjustable member for varying the mold-cavity widthwise of the type to be formed; controlling mechanism for bringing each matrix separately in conjunction with the mold; a normal adjusting mechanism operating through the adjustable member of the mold, to vary the size of the mold-cavity and proportion the latter to the dimensions of the character or space represented by each selected matrix; justifying mechanism adapted to vary the normal dimensions of the mold-cavity as determined by the normal adjusting mechanism; a single perforated controlling-strip; and a pneumatic controlling system governed by or from the controlling-strip and operating to effect the centering of the matrices, to set the justifying mechanism, and to connect the justifying mechanism with the movable member of the mold at predetermined intervals.
2. In a type-making machine such as described, the combination of the following elements, to wit; a series of movable matrices; a mold provided with an adjustable wall or member for varying the width of the mold-cavity; controlling mechanism for shifting the matrices to bring any one of them in conjunction with the mold; normal mold-adjusting mechanism operating upon the adjustable member of the mold to vary the size of the mold-cavity to correspond with the selected matrix; justifying mechanism operating to vary the normal adjustments of the mold; a pump and nozzle for injecting molten metal into the mold; a perforated controlling-strip; and a pneumatic system governed by the controlling-strip and connecting the latter with the controlling mechanism for the matrices, the justifying mechanism and the pump-operating devices.

3. In a type making and setting machine such as described, the combination of the following elements, to wit; a mold furnished with an adjustable member or section for varying the width of the mold-cavity and a removable section opposite said adjustable section; a normal adjusting and justifying mechanism connected to the movable section of the mold for controlling the width of the types cast in said mold; a series of matrices with controlling mechanism for bringing each matrix separately in conjunction with the mold; injecting mechanism for supplying molten metal to the mold; a galley mechanism provided with type-carrying, line-forming and line-transferring devices; a perforated controlling-strip; and a pneumatic system governed by the controlling-strip and acting upon the injecting, justifying, matrix-

controlling, and galley-operating mechanisms, to control the delivery of molten metal into the mold, to set the justifying mechanism for the line and connect it at predetermined intervals, to bring successive matrices into position and effect the normal adjustments of the mold, and at the completion of a line to transfer the latter to the galley; substantially as described.

4. In a type-making machine such as described, the combination of the following elements, to wit; a mold provided with an adjustable wall or section for varying the width of the mold-cavity; a series of dies or matrices each adapted to be brought into co-operative relation with the mold to form individual types; actuating mechanism for centering individual dies or matrices and effecting the normal adjustment of the mold; said actuating devices being provided with a series of controllable stops or devices for determining the positions of the matrices or dies and of the adjustable section of the mold; abnormal adjusting or justifying mechanism acting through the adjustable section of the mold to vary the normal adjustments thereof and provided with a controllable member through which latter the matrix-actuating mechanism may be utilized to effect the adjustment of the justifying mechanism and further provided with a driver or operating device and a controlling member for rendering the justifying mechanism operative upon the movable section of the mold; a perforated controlling-strip; and a pneumatic system governed by the controlling-strip and in turn governing the controllable devices of the matrix-actuating mechanism and of the justifying mechanism.

5. In a machine for forming justified lines of types, the combination of the following elements, to wit; a mold provided with an adjustable wall or section for varying the width of the mold-cavity; a movable die-case provided with actuating mechanism, including controllable stop devices for separately locating each die in conjunction with the mold; normal mold-adjusting mechanism for effecting variations in the width of the mold-cavity; justifying mechanism provided with controllable adjusting devices and controllable actuating or connecting devices; a metal-injecting mechanism provided with controllable connections; a galley mechanism provided with a type-carrier receiving the types from the mold and transferring them to a line-holder and a line-transferring mechanism for moving the completed line into the galley; a perforated controlling-strip; and a pneumatic system governed by the controlling-strip and having separate connections with the controllable members of the die-case-actuating mechanism, the justifying mechanism, the injecting mechanism and the line-transferring devices of the galley mechanism.

6. In a machine for making justified lines of types the combination with the mold and

its movable section, the die-case and its actuating mechanism; the normal adjusting and the justifying mechanism; the metal-injecting mechanism; the resetting mechanism for the justifying mechanism; and the galley mechanism, of a perforated controlling-strip and a pneumatic system governed thereby, the latter controlling the movements of the die-case, the adjustments of the justifying mechanism, the application of the justifying mechanism to the movable section of the mold, the metal-injecting mechanism, the galley mechanism and the resetting devices of the justifying mechanism.

15 7. In a machine for making justified lines of types, the combination with an adjustable mold, a movable die-case, a normal adjusting mechanism for the mold, an abnormal adjusting or justifying mechanism, and metal-injecting mechanism, of a controlling-strip and a controlling system governed thereby, the latter including connections operating upon the die-case to center each die opposite the mold, upon the justifying mechanism to determine the amount of variations required to justify the line, and to apply said variations, and upon the injecting mechanism to suspend its action when desired.

8. In a machine for making justified lines 30 of types the combination with the adjustable mold, the movable die-case, the justifying mechanism, the metal-injecting mechanism and the resetting devices for the justifying mechanism, of a perforated controlling-strip 35 and a controlling system governed by said strip, said system including connections operating upon the die-case-actuating mechanism to control the position of the dies with reference to the mold; upon the justifying 40 mechanism to set the latter for the line and establish operative connection with the adjustable section of the mold when certain designated dies are centered; upon the injecting mechanism to suspend its action; and upon 45 the resetting device of the justifying mechanism to return the latter to the starting position.

9. In a type-making machine, the combination of the following elements, to wit; a movable series of dies or matrices with actuating devices therefor deriving motion from a main driving-shaft and provided with a series of stopping or limiting devices for arresting the motion of the series of dies with any one in 55 the centered or casting position; a mold for forming the bodies of the types provided with an adjustable section for varying the width of the mold to form types of different widths; normal adjusting mechanism controlling the 60 position of the adjustable mold-section; a perforated controlling-strip; and a pneumatic system governed by the controlling-strip and operating the limiting or stopping devices of the dies or matrices.

65 10. In a machine for making justified lines of type, the combination of the following elements, to wit; a main driving-shaft; a fixed

mold with an adjustable section for varying the width of the mold-cavity therein; a die-case supported to move in transverse directions; two actuating mechanisms, each controlling the movements of the die-case in one direction, driven from the main shaft through flexible connections and provided with a series of controllable stops for arresting the 75 die-case during different portions of its traverse, to center any one of the dies or matrices opposite the mold; a justifying mechanism for controlling the position of the adjustable section of the mold, said justifying mechanism being provided with an adjustable member 80 operated from the die-case-actuating mechanism through a controllable member or pawl, and a driver operated from the main shaft and connected through a controllable 85 pin or member with the adjustable section of the mold; a pump and nozzle for injecting molten metal into the mold, with actuating mechanism driven from the main shaft to connect the nozzle with the mold and operate the pump; a strip containing perforations for controlling the action of the machine; and a pneumatic system governed by the controlling-strip and containing ports, passages and pistons, the latter operating the 90 controllable stop of the die-case-actuating mechanism pawl and pin of the justifying mechanism, and a disengaging device intermediate the pump and driving-shaft for controlling the action of the pump.

100 11. In a machine for making justified lines of types containing as its principal elements a movable die or matrix case, an adjustable mold, normal adjusting and justifying mechanisms for the mold, and a perforated controlling-strip, the combination therewith of a pneumatic controlling system governed by the perforated strip and operating the controlling-stops for determining the position of the die-case and the adjustment and connection of the justifying mechanism.

115 12. In a machine for making justified lines of types containing in its organization a movable die-case containing a series of matrices; a mold adjustable as to width of the cavity; 115 normal and abnormal or justifying mechanisms for adjusting the mold; a metal-injecting mechanism; and a perforated controlling-strip, the combination therewith of a pneumatic controlling system governed by the perforated strip and controlling the position of the movable die-case, the adjustment and application of the justifying mechanism, and the action of the injecting apparatus.

120 13. In a machine for making justified lines of type, the same being provided with a movable series of matrices, a mold having an adjustable member and metal-injecting apparatus co-operating with the mold to deliver molten metal therein after the mold has been 125 adjusted and the selected matrix brought into conjunction therewith, the combination of a normal adjusting mechanism controlled by or from the actuating devices for the matrices 130

and acting upon the adjustable section of the mold to vary the width of the latter, an abnormal adjusting or justifying mechanism operating through or upon the normal adjusting mechanism, to vary the extent of adjustment produced thereby, a controlling-strip containing perforations representing the selected matrices and justification-index for the line, and a pneumatic system governed by the controlling-strip and including the controllable members of the matrix-actuating mechanism and of the justifying mechanism.

14. In a machine for making justified lines of type provided with a movable series of matrices, a mold having an adjustable member, and metal-injecting mechanism, the combination of normal adjusting mechanisms connected to the adjustable member of the mold and controlled by the actuating mechanism of the matrices, an abnormal adjusting or justifying mechanism acting through the adjustable member of the mold to vary the normal adjustments thereof and provided with controllable actuating devices for determining the degree of variation; controllable connecting devices for determining the time or occasion of its application to the mold and controllable resetting devices; a controlling-strip provided with perforations representing the selected matrices, the degree of variation for justification and the time or occasion for the application of the justifying mechanism to the mold and the resetting of the justifying mechanism; and a pneumatic system governed by the perforated strip and controlling the location of the matrices, the degree of adjustment of the justifying mechanism, the time or occasion of the application of the justifying mechanism and the resetting of the justifying mechanism.

15. In a machine for producing justified lines of types provided with a movable series of matrices, a mold having an adjustable section for varying the width of the cavity and a movable section, normal justifying mechanism acting through the adjustable section of the mold to vary its position to correspond with the selected matrix, abnormal adjusting or justifying mechanism operating to vary the position of the adjustable section of the mold, metal-injecting mechanism, and a galley mechanism receiving successive types from the mold, arranging them in lines and transferring the lines to a galley, the combination therewith of the perforated controlling-strip, and the pneumatic system governed by said strip and operating the controllable members of the mechanism for locating the matrices, for setting the justifying devices, for applying the justifying devices, for controlling the injection of molten metal into the mold, for effecting the transfer of the completed line to the galley and for resetting the justifying mechanism.

16. In a machine for making justified lines of types adapted to be controlled by a single strip perforated to represent the individual

types which are to compose the line, the types to be varied in width as compared with the normal, to effect justification, the degree or amount of variation for each of the selected types to produce justification, and resetting of the justification mechanism preliminary to the formation of the next line, the combination with such a controlling-strip of a mold in which the body portions of the types are formed; a series of movable matrices or dies coöperating with the mold to form and determine the face of the type, with controllable devices for locating the several matrices or dies; justifying mechanism for varying the width of the mold-cavity, said mechanism including controllable devices for adjusting the same to produce the desired degree of variation for resetting the adjustable member, and for rendering the adjustable member operative to affect the width of the mold; and a pneumatic system intermediate the perforated strip and each of the said controllable members of the matrix adjusting and justifying mechanisms.

17. In a machine for making justified lines of types adapted to be controlled by a single strip perforated at intervals to represent the individual types on a line, the types to be varied in width as compared with the normal to effect justification, the amount or degree of variation for each of the selected types, the suspension of the casting operation, and the resetting of the justification mechanism, preliminary to its adjustment for the next line, the combination with said controlling-strip of a mold adjustable in width; a series of movable matrices or dies coöperating with the mold and provided with controllable devices for determining the location of the several matrices opposite the mold; justifying mechanism for varying the width of the mold provided with controllable devices for effecting its adjustment, for resetting it, and for causing it to operate upon the mold; a metal-injecting apparatus furnished with a controllable stop for arresting the flow of metal to the mold; and a pneumatic system governed by the perforated strip and including the controllable members of the matrix mechanism, of the justifying mechanism and of the injecting mechanism.

18. In a machine for making justified lines of type adapted to be controlled by a single strip perforated at intervals to represent the individual types comprising the line, the degree of variation to be effected in width of some or all of the types, the stopping of the flow of molten metal, the resetting of the justifying mechanism and the transfer of the completed line to the galley, the combination with said controlling-strip of the mold; the movable series of matrices; the justifying mechanism; the metal-injecting mechanism, a galley mechanism; and the pneumatic system governed by said strip and actuating the controllable members of the matrix-shifting mechanism, of the justifying mechanism, of

the metal-injecting mechanism, and of the galley mechanism.

19. A die-case provided with an open frame and a series of independent die or matrix blocks loosely suspended upon transverse rods, the latter supported at the ends in said frame; substantially as described.

20. A die-case, comprising an open frame, a series of die or matrix blocks arranged in parallel lines within said frame, each line of blocks loosely supported upon a rod extending transversely through all the blocks in the line and attached at its ends to the side bars of the frame; substantially as described.

21. A die-case for use in a machine such as described, the same including an open frame, a series of die or matrix blocks each provided with a transverse perforation a matrix-cavity or die-face at one end, and a conical or tapering centering-recess at the opposite end, said blocks being loosely supported in lines upon parallel rods whose opposite ends are held in bearings in the side bars of the frame.

22. In a machine such as described, the combination with the support-plate sustained upon elastic supports permitting vertical movement, of the supporting-frame mounted to reciprocate horizontally upon said supporting-plate, and the die-case carried by said supporting-frame and capable of reciprocating horizontally thereon in a direction transverse to the line of movement of said supporting-frame upon the supporting-plate.

23. The combination of the die-case mounted to reciprocate in transverse lines and provided with a series of independent matrix-blocks each furnished with a conical centering-aperture; yielding supports for said die-case permitting movement of the latter in a direction transverse to its first-named reciprocating motions; and a plunger provided with a tapering pin adapted to enter the conical aperture of the die-block when brought opposite thereto, and, by its forward motion, to first center the die-block, and then advance the die-case; substantially as and for the purpose set forth.

24. The combination with the die-case, the supporting-frame, the supporting-plate and the plunger, of the means for guiding and sustaining the supporting-plate and actuating the plunger, to center the die or matrix blocks and reciprocate the die-case and its supports, the same comprising the rods attached to the supporting-plate, the yoke connecting said rods, the springs for retracting and holding the supporting-plate and its attachments, the two collars on the plunger, the loose sleeve and spring interposed between said collars, and the actuating-lever engaging the sleeve.

25. In combination with the horizontally-reciprocating and vertically-movable die-case provided with a series of independent matrix or die blocks, the vertically-reciprocating plunger provided with a centering device for engaging and centering the matrix-blocks, yielding supports, such as springs, for up-

holding the die-case so that the plunger will operate to first center the matrix-block and then depress the die-case.

26. In a type-making mechanism, the combination of a stationary mold; a die-case provided with a series of independent matrix-blocks and supported to reciprocate in a plane substantially at right angles to the axis of the mold, and to move bodily toward and from the mold; yielding devices for holding the die-case normally removed from the mold; a centering-plunger reciprocating toward and from the mold and engaging the interposed matrix-block, to first center it and then advance the die-case toward the mold and hold the centered matrix-block tightly against the end of the mold; devices for actuating the die-case to locate the matrix-blocks in line with the plunger and actuating devices for the plunger.

27. In a type-making mechanism the combination of the mold; the movable die-case provided with a series of independent matrix-blocks; actuating devices for shifting the die-case to bring any one of the matrix-blocks in line with the mold; a reciprocating plunger provided with a centering device for centering the matrix-block, advancing the die-case toward the mold, and seating the centered matrix-block against the mold; and actuating mechanism for the plunger furnished with a yielding device serving to maintain the matrix-block in position on the mold under elastic pressure, and permitting it to yield in case an obstacle is encountered.

28. As a means for locating or positioning any one of a series of dies or matrices opposite to a centering point or station, the combination of a die case or carrier supported to reciprocate across the centering-point and provided with dies or matrices arranged serially in the direction of the motion of the die-case; driving member, such for example as a lever, to which a reciprocating motion of uniform extent is imparted; a yielding connection between said reciprocating driving member and the die-case such as will permit the latter to be arrested while the driving member continues in motion; and a series of controllable stops located in proximity to the path traversed by the die-case or some part connected and moving in unison therewith, said stops being spaced to correspond with the serial spacing of the dies or matrices, so that when any one of said stops is projected into the path of the die-case or a part connected therewith, it will serve to arrest the motion of the die-case with the corresponding die or matrix at the centering-point.

29. The combination of a die-case supported to reciprocate transversely of or across the centering point or station, and provided with a plurality of dies or matrices serially arranged in the direction of the reciprocating movements of the die-case; a driving member or lever to which a uniform degree of motion is imparted; a yielding connection between

said driving member and the die-case, causing the two to normally reciprocate in unison but permitting the die-case to be arrested while the driving member continues in motion; and a plurality of stops, each adapted to be projected into the path traversed by a part connected to and reciprocating in unison with the die-case, said stops being spaced to correspond with the serial spacing of the matrices or dies and operating to arrest the die-case with the corresponding die or matrix at the centering-point.

30. In combination with the reciprocating die-case, its reciprocating driving member or lever, and the interposed yielding connection through which the motion of the driver is communicated to the die-case, a pawl mounted to reciprocate in unison with the die-case, a fixed series of teeth with which said pawl is adapted to coöperate and a series of controllable stop-pins adapted to be separately projected into the path traversed by the pawl and, by engaging the latter, to throw the pawl into engagement with the teeth and thus arrest the die-case.

31. In combination with the reciprocating die-case, the slide connected thereto, the reciprocating driving member or lever having a uniform excursion, and the yielding connection between said driving member and the slide, of the two-armed pawls carried by said slide, the ratchet-plates, and the stop-pins for operating upon the pawls to cause their engagement with the ratchet-plates and thereby arrest the movement of the die-case at any of the different points in its traverse determined by the position of the stop-pin employed for the purpose.

32. The combination of a die-case mounted to reciprocate and provided with a plurality of dies or matrices; and two independent actuating mechanisms operating in intersecting planes on the die-case, to control its position, each of said actuating mechanisms comprising a driving member, an intermediate yielding connection, a pawl or pawls reciprocating in unison with the die-case, ratchet-teeth, and a series of controllable stop-pins for causing the engagement of the pawl or pawls with the ratchet-teeth, to arrest the die-case at different points in its movement.

33. The combination in a type-making mechanism such as described, of the following elements, to wit; a stationary mold; a die-case provided with a plurality of dies or matrices and supported to reciprocate across the end of the mold; two actuating mechanisms controlling the movements of the die-case in intersecting planes, each of said mechanisms including a driving member, a yielding connection, pawls, ratchet-teeth, and controllable stop-pins; and a centering-plunger operating to center the selected die or matrix opposite the mold, and press and hold it in contact with the latter while the type is being formed.

34. The combination in a type-making mechanism such as described, of the following elements, to wit; a stationary mold; metal-injecting mechanism; a die-case provided with independent matrix-blocks arranged serially on intersecting lines, said die-case being mounted to reciprocate transversely of and across the end of the mold; two actuating mechanisms for controlling the position of the die-case, acting on intersecting lines and each provided with a reciprocating pawl or pawls, fixed ratchet-teeth, and controllable stop-pins; and a plunger provided with a centering device for engaging the selected matrix-block and bring it into contact with the mold preliminary to the injection of the metal therein.

35. In a type-forming mechanism the combination of the following elements, to wit; a stationary mold; a centering-plunger in line with and opposite one end of said mold; a die-case arranged to reciprocate between the plunger and mold in a plane at right angles to the axis of the mold and plunger, said die-case being provided with a series of independent matrices; two actuating mechanisms operating at right angles to control the movements and position of the die-case, each of said mechanisms comprising a driving member having a uniform degree of motion, a yielding connection, reciprocating pawls, stationary ratchet-teeth and controllable stop-pins; and mechanism for actuating the plunger, to center the selected matrix and hold it in contact with the mold.

36. In a type-making mechanism such as described, the combination of the following parts, to wit; the stationary mold; and die-case and its supports including the supporting-frame and the supporting-plate; and two die-case-actuating mechanisms, the one connected to the die-case and the other to the supporting-frame, and each including a driving-lever operated from a cam on the main shaft, a slide attached to the driving-lever through an intermediate flexible connection, pawls mounted upon the slide, stationary ratchet-teeth, and controllable stop-pins for throwing the pawls into engagement with the ratchet-teeth.

37. In a die-case-operating mechanism such as described the combination with a reciprocating driver, a die-case mounted to reciprocate, and an interposed yielding connection through which motion is transmitted from the driver to the die-case, of a series of ratchet-teeth, a series of stop-pins and a pawl connected to and reciprocating in unison with the die-case, said pawl being arranged to be engaged by the stop-pins when projected into its path and to engage the ratchet-tooth corresponding to the stop-pin, to arrest the movement of the die-case, the angle of the engaging faces of the ratchet-teeth and pawl being such as to slightly augment the throw of the pawl as produced by contact with the stop-

pin, whereby the shock is transferred to and borne by the ratchet, and the pawl is swung from contact with the stop-pin.

38. The combination with the reciprocating driving member or lever, the slide, and the yielding connection between the driver and slide; of a series of stationary ratchet-teeth; a pawl pivoted on said slide in position to engage the ratchet-teeth but normally held from contact therewith; a series of stop-pins each adapted to be projected into the path traversed by the pawl, and, by engaging the latter to throw it into contact with one of the ratchet-teeth; and pneumatic operating devices for controlling the positions of the stop-pins.

39. In a type-forming mechanism, the combination with the mold, of the supporting-plate and plunger carried by a detachable block or section of the frame; and the die-case and its supporting-frame each detachably connected to its actuating mechanism.

40. In a machine such as described, the combination of the suspended supporting-plate, the supporting-frame guided to reciprocate longitudinally of the supporting-plate and connected by a link to its controlling-slide; the die-case mounted to reciprocate on the supporting-frame in a direction crosswise of the supporting-plate, and connected by a link to a rod on its controlling-slide, said rod permitting independent movement of the die-case with the supporting-frame in a direction at right angles to that of the die-case-controlling slide.

41. In a machine such as described, the combination with the reciprocating driving member, the die-case and the yielding connection, of the slide carrying two pawls standing in opposite directions, two series of ratchet-teeth, one for each pawl, and a series of stop-pins for throwing either pawl into engagement with the corresponding ratchet-tooth, said stop-pins being arranged serially, and alternately on opposite sides of the slide, so that successive stop-pins will engage alternately opposite pawls.

42. A mold adapted for use in conjunction with detachable matrices, provided with fixed side walls, 80, 81, an adjustable mold-blade 96, movable between the side walls, and a movable front wall 83.

43. In a mold adapted for use in connection with a removable matrix, the combination of the fixed side walls, the adjustable mold-blade and the movable wall 83 carried by a slide containing the jet opening or recess.

44. The combination in a mold such as described, and with the fixed blocks constituting the side walls of the mold-cavity and the adjustable mold-blade, of the movable front wall attached to a slide, the latter provided with a portion extending beneath the fixed blocks and containing the jet passage or opening.

45. The combination in a mold such as de-

scribed and with the fixed blocks forming the side walls and the adjustable mold-blade, the reciprocating slide carrying the front wall of the mold and provided with a transverse groove or recess extending beneath the fixed blocks, the jet-blade located in said groove or recess, and the fixed cam engaging said jet-blade to expel the jet after the type has been formed and as the slide is moved to open the mold.

46. In a type-forming mechanism such as described, the combination of the following elements, to wit; a movable series of matrices, with devices for bringing any one to the casting-point; a stationary mold; a movable jet-slide; and a reciprocating nozzle through which molten metal is projected through the jet-pressure into the mold; said jet-slide being moved at the completion of the casting operation and before the withdrawal of the nozzle, to cut off or separate the jet from the type and cover the nozzle-seat.

47. In a type-forming mechanism such as described, the combination of the following elements, to wit; a movable series of matrices, with means for centering any one at the casting-point in contact with the mold; a stationary mold; a jet-slide traversing beneath the mold and provided with a movable jet-blade; a nozzle-seat, a movable nozzle, with means for ejecting molten metal through the jet-passage into the mold; and actuating devices controlling the movements of the nozzle and jet-slide so that after the metal has been injected into the mold and while the nozzle is on its seat, the jet-slide will be moved to sever the jet from the type and cover the nozzle-seat.

48. In a type-forming mechanism such as described, the combination of the following elements, to wit; a movable series of matrices; a stationary mold provided with fixed side walls, an adjustable mold-blade and a movable front wall; a jet-slide provided with a jet-ejecting blade; a nozzle-seat below the jet-slide; and a metal-injecting apparatus provided with a nozzle movable toward and from its seat, said jet-slide being operated to cut off the jet while the nozzle remains seated; substantially as described.

49. In a type-forming mechanism, the combination with the mold, the nozzle of the metal-injecting apparatus, and the nozzle-seat, of a movable jet-slide interposed between the nozzle-seat and mold, and moved to sever the jet while the nozzle remains in position and before or simultaneously with its withdrawal from its seat.

50. In a type-forming mechanism, the combination of the following elements, to wit; a movable series of matrices provided with devices for locating and centering any matrix of the series at the casting-point; a stationary mold composed of fixed side walls, an adjustable and movable blade for determining the width of the mold-cavity and ejecting the type therefrom, and a movable wall for

uncovering the front of the mold-cavity and permitting the escape of the type therefrom; a nozzle-seat; a reciprocating nozzle with means for ejecting molten metal therefrom; a jet-slide intermediate the nozzle-seat and mold; and a jet-blade carried by the jet-slide and operating to eject the jet therefrom after it has been severed from the type.

5 51. In a type-forming mechanism such as described and in combination with the mold provided with an adjustable section or mold-blade for varying the width of the mold-cavity, of actuating devices for reciprocating the mold-blade and automatically-operated stop mechanism for arresting the movement of the mold-blade intermediate the extremes of movement of the actuating devices.

10 52. In a type-forming mechanism such as described, the combination with the mold provided with a movable mold-blade of actuating devices for reciprocating the mold-blade to discharge the type from the mold, and automatically-adjustable controlling mechanism for arresting the mold-blade during its retrograde movement after ejecting the type, to set the mold for the next succeeding type.

15 53. In a type-forming mechanism such as described, the combination of the following elements, to wit; a movable series of matrices with mechanism for locating any matrix at the casting-point; a mold provided with an adjustable mold-blade; actuating devices for reciprocating said mold-blade and controlling devices for arresting the movement of the mold-blade and thereby determining its position in the mold.

20 54. In a type-forming mechanism such as described the combination of the following elements, to wit; a movable series of matrices; a mold operating in conjunction with any one of said matrices and provided with an adjustable section or mold-blade for varying the width of the mold-cavity and ejecting the type therefrom, and a movable section for opening the mold so as to permit the escape of the type; actuating devices operating to reciprocate the mold-blade; and controlling devices for limiting the movement of the mold-blade as it is retracted after discharging a type, to adjust its position and the width of the mold-cavity preliminary to the formation of the next succeeding type.

25 55. In a type-forming mechanism such as described, as a means for adjusting the position of the mold-blade in the mold, the combination with said mold-blade, of the slide; the actuating-lever deriving motion from the main driving-shaft; the stop-rod; and the normal wedge operating to vary the position of the stop-rod, and, through the latter, to arrest the mold-blade in adjusted position.

30 56. In a type-forming mechanism such as described, the combination of the following elements, to wit; a series of movable matrices with mechanism for centering any one of said matrices opposite the mold; a mold provided

35 with a movable mold-blade for varying the width of the mold-cavity; actuating devices for reciprocating the mold-blade; a stop-rod 70 controlled by a wedge for limiting the movement of the mold-blade in one direction; and connections between the wedge and the mechanism for centering the matrices, for shifting the wedge to correspond with the selected 75 matrix.

40 57. In a type-forming mechanism such as described, the combination of the die-case provided with matrices graded serially according to width; controllable actuating devices for shifting the die-case; a mold furnished with an adjustable mold-blade and a movable member or wall opposite thereto; actuating devices for reciprocating the mold-blade, to discharge the type; a stop-pin for 85 arresting the mold-blade during its return motion, to adjust the width of the mold-cavity; a normal wedge controlling the position of said stop; and connections for shifting said normal wedge in unison with the die-case. 90

45 58. In a type-forming mechanism such as described, the combination with the die-case, the mold, the actuating mechanism for reciprocating the die-case in one direction, the slide, pawls and stop-pins for limiting the 95 motion of the die-case and the stop for limiting the motion of the mold-blade, of the normal wedge connected to reciprocate in unison with the slide carrying the pawls, and governed, as to position, by the same stop-pin 100 which serves to govern the position of the die-case.

50 59. The combination with the pawl-carrying slide of the die-case-actuating mechanism and the normal wedge of the mold-blade-controlling mechanism, of the connecting-lever and the driving-lever provided with a rod the latter bearing a spring and a pin or shoulder between which the connecting-lever is received thus forming a yielding connection 110 which will permit the wedge and slide to be arrested while the driving-lever continues in motion.

55 60. The combination with the die-case-actuating mechanism and the normal wedge for 115 controlling the mold-blade, of the connecting-lever and the micrometer or adjusting device for varying the position of the wedge with relation to the die-case-controlling devices.

60 61. In a type-forming mechanism such as 120 described the combination of the following elements, to wit; the die-case and its actuating mechanisms for controlling its movements in two directions; the mold provided with a movable mold-blade; mold-blade actuating 125 and controlling mechanisms including the normal wedge, the latter connected to one of the die-case-actuating mechanisms and moving in unison with the die-case, to vary the width of the mold; and a justifying mechanism operating to shift the position of the normal wedge laterally, to vary its effect upon the mold-blade. 130

65 62. In a mechanism for forming justified

lines of types such as described the combination of the following elements, to wit; a die-case controlled, as to its movements for bringing any die or matrix to the center point, by 5 two actuating mechanisms operating relatively in transverse directions, said actuating mechanisms each deriving motion from reciprocating drivers or levers having a uniform range of motion and provided with a yielding 10 connection and controllable stops for arresting the motion of the die-case; a mold located at the centering-point for the die-case and provided with a mold-blade for varying the width of the mold; controlling mechanism, including 15 the normal wedge, for adjusting the position of the mold-blade to correspond with the width of the selected or centered matrix; and a justifying mechanism acting through the normal wedge to vary the adjustment of the 20 mold-blade.

63. In a machine for forming justified lines of types, the combination of the following elements, to wit; the die-case; the mold with movable mold-blade; the normal wedge reciprocating in unison with the die-case and controlling the position of the mold-blade; and a justifying mechanism operating to vary the position of the mold-blade, said justifying mechanism receiving its movement of adjustment 25 from the controllable actuating mechanism of the die-case through a controllable member, and acting upon the mold-blade only when connected to a driver through a controllable member, whereby the actuating mechanism 30 of the die-case is utilized to set the justifying mechanism, and the latter can be rendered operative upon the mold-blade during the formation of any types which are to form the line.

40 64. In a type-forming machine such as described, the combination of the following elements, to wit; the die-case and its two actuating mechanisms each furnished with a series of controllable stops for limiting the movements 45 of the die-case; the mold provided with a movable mold-blade, the normal wedge for adjusting the mold-blade, said wedge receiving motion from one of the die-case-actuating mechanisms and having its position determined by the controllable stop-pins there- 50 of; a justifying mechanism, furnished with an adjustable member; connections between the other die-case-actuating mechanism and the adjustable member of the justifying mechanism, including a controllable member, whereby the movement of the die-case-actuating mechanisms as effected by its controllable stops may be utilized to set the adjustable member of the justifying mechanism 55; a reciprocating driver for actuating the justifying mechanism, to render it operative upon the mold-blade; and a controllable connecting member for said driver.

65 65. In a justifying mechanism for varying the position of the mold-blade, the combination with the pivoted frame with which the mold-blade-adjusting devices are connected,

of the driving-slide reciprocated in said frame, the adjustable head carrying the compound slide, and the controllable pin for connecting 70 the compound slide to the driving-slide for transmitting motion to the pivoted frame and through the latter to the mold-blade.

66. In a justifying mechanism for controlling the position of the mold-blade, the combination with the pivoted frame to which the mold-blade-controlling devices are connected, of the reciprocating driving-slide, the pivoted adjustable head or member, the compound slide engaging the said adjustable head and 80 pivoted frame, and the controllable pin for connecting the compound slide with the driving-slide.

67. In a justifying mechanism for determining the width of the mold, the combination of the pivoted frame, the pivoted adjustable head, the compound slide engaging the said frame and head, the driving-slide mounted upon the pivoted frame, the controllable pin carried by the compound slide 90 for engaging the driving-slide, and the latch for retaining the pin in position.

68. In a justifying mechanism for a type-making machine the combination of the normal wedge and its supporting-frame; the pivoted frame connected to the normal-wedge frame and controlling its position and that of the mold-blade; the adjustable pivoted controlling member or head; the compound slide composed of two sections pivoted together, 100 the one riding in ways in the adjustable controlling-head and the other in ways in the pivoted frame; the driving-slide reciprocating upon the pivoted frame; the controllable pin carried by the compound slide and adapted to engage the driving-slide; and a latch carried by the driving-slide for engaging the pin, to retain it temporarily in position.

69. In a machine for forming justified lines of types the combination of the following elements, to wit; a type-mold provided with an adjustable mold-blade; controlling devices, including the normal wedge, for adjusting the mold-blade; a frame normally parallel with the normal wedge, pivoted at one end and connected to the movable support of the normal wedge; a driving-slide mounted to reciprocate longitudinally of the pivoted frame; an adjustable head or guide pivotally supported beneath the pivoted frame, with its axis parallel with that of said frame; a compound slide whose sections are pivotally connected, the one riding in ways in the pivoted frame and the other in the adjustable head; a pin carried by said compound slide and adapted to enter an orifice or seat in the driving-slide; and a latch carried by the driving-slide for engaging the pin, said latch being operated by an obstruction on the pivoted frame, to disengage said pin at the completion of the stroke of the driving-slide so as to disconnect the compound slide from its driver.

70. In a type-forming machine such as de-

scribed, the combination with the adjustable head or member of the justifying mechanism which determines the variation in the width of the type formed in the mold, of a driver, controlled as to the extent of its movement, by the stop-pins of the die-case-actuating mechanism, and, as to the time or occasion of its operative connection with the devices for transmitting motion to said adjustable member, by a separate controllable member, whereby the movements of the die-case-actuating mechanisms are utilized to determine the extent of the adjustment while the time when the adjustment is to be effected is separately controlled.

71. In a machine for forming justified lines of types, the combination substantially as described of the following elements, to wit; the die-case and actuating mechanism therefor; the mold provided with an adjustable mold-blade; the adjustable head or member of the justifying mechanism by means of which the degree of variation in the position of the mold-blade is effected or controlled; operating devices, including a ratchet-wheel for shifting the position of said adjustable head or member; a driving-pawl connected to reciprocate with the die-case-actuating mechanism and held normally from contact with the ratchet-wheel; and controllable means for throwing the pawl temporarily into engagement with the ratchet-wheel.

72. In a justifying mechanism for type-forming machines the combination of the following elements, to wit; an adjustable head or member for controlling the degree of adjustment given the mold; a ratchet-wheel operating through suitable transmitting devices upon said adjustable head or member; a reciprocating pawl held normally from engagement with the ratchet-wheel and connected to controllable means for effecting engagement therewith; a holding-pawl for maintaining the ratchet-wheel in adjusted position; a returning-spring and stop; and controllable means for withdrawing the holding-pawl and permitting the return of the ratchet-wheel to its initial position.

73. In a type-forming mechanism such as described, the combination of the following elements, to wit; the reciprocating slide carrying a pawl in position to engage fixed ratchet-teeth and controlled as to extent of motion by controllable stop-pins; a rack connected to and moving with said slide; a gear-segment engaged by the rack, pivoted on a shaft, and carrying a pawl, the latter held normally retracted and provided with controllable means for throwing it into operative relation to the part to be driven thereby; a ratchet-wheel, worm and returning-spring attached to the shaft upon which the said gear-segment is pivoted; the holding-pawl provided with controllable means for detaching it from the ratchet-wheel, to permit the return of the latter under the influence of the spring; and the adjustable head or mem-

ber, for controlling the degree of variation on the width of the mold, provided with a worm-segment engaging the worm.

74. In a justifying mechanism for type-forming machines such as described, the combination of the following elements, to wit; a mold provided with an adjustable section or mold-blade; an adjustable head or member connected medately to the mold-blade; a controllable device for rendering the adjustable head operative upon the mold-blade; to effect the prescribed adjustment of the latter; a ratchet-wheel connected through suitable transmitting devices, to the adjustable head; a driving-pawl held normally from engagement with the ratchet-wheel and provided with controllable means for throwing it into engagement with the ratchet-wheel; a holding-pawl for the ratchet-wheel provided with controllable means for effecting its withdrawal or disconnection from said wheel and an actuating mechanism governing the reciprocations of the driving-pawl; provided with controllable stops for determining the length of the reciprocating movements of the said pawl.

75. In a justifying mechanism such as described the combination with the adjustable head for varying the width of the mold-cavity, the pivoted frame, and the compound slide, of the reciprocating driving-slide, and the controllable connecting-pin, provided with a piston and cylinder, the whole carried by the compound slide in position to engage the driving-slide.

76. In a justifying mechanism such as described the combination with the ratchet-wheel connected to and actuating the adjustable member which determines the variation in width of the mold, of the pawl mounted upon a reciprocating support, devices for controlling the extent of movement of the pawl-support, and a piston and cylinder carried by said pawl-support and controlling the application of the pawl to the ratchet-wheel.

77. In a justifying mechanism such as described, the combination of the adjustable head or member for controlling the extent of variation in width of the mold; a controllable member operated by a piston and cylinder for operatively connecting the movable section of the mold to said adjustable head or member; adjusting devices for said adjusting head or member provided with a piston and cylinder for controlling the connection between the transmitting and driving members thereof; and a piston and cylinder controlling the release or resetting devices, substantially as described, whereby fluid-pressure may be employed to operate the said pistons and control the setting and resetting of the adjustable member, and the times of its application to the mold.

78. In a type-forming machine the combination substantially as described, of the mold; the fixed nozzle-seat; and the reciprocating

nozzle, pump and melting-pot, the latter supported upon trunnions or pivots movable toward and from the nozzle-seat, to compensate for expansion and contraction.

5 79. In a type-forming mechanism the combination substantially as described of the mold; the stationary nozzle-seat; the reciprocating jet-slide; and a metal-injecting apparatus containing nozzle, pump and melting-
10 pot pivotally supported and reciprocating in movable bearings, whereby the injecting apparatus is automatically adjusted by the engagement of the nozzle with its seat.

80. In a type-casting mechanism the combination substantially as described of the mold, the stationary conical nozzle-seat, and the self-adjusting and reciprocating nozzle, pump and melting-pot.

81. In a type-casting mechanism the combination substantially as described, of the horizontally-adjustable casing; the melting-pot and nozzle pivotally supported on said casing to reciprocate vertically in movable bearings; and centering or adjusting devices 25 engaging the nozzle as it is vibrated to position and operating thereon to shift the bearing to compensate for expansion and contraction and insure the seating of the nozzle.

82. In a type-casting mechanism the combination substantially as described of the melting-pot pivotally supported on movable bearings; the fixed conical nozzle-seat; and the mechanism for oscillating the melting-pot on its pivots, said mechanism being connected to the melting-pot at a point remote from its pivots and comprising the link, bell-crank lever and cam-actuated rod provided with a compression device.

83. In a type-casting mechanism the combination substantially as described of the mold; a reciprocating melting and injecting apparatus composed of a pivotally-supported melting-pot, pump and injecting-nozzle; a nozzle-seat; and mechanism operating the piston of the pump provided with driving and driven members or levers, a connecting-pin borne by a slide, actuating mechanism provided with a compression device for reciprocating said slide, to alternately connect and disconnect the driving and driven members, and a controllable stop for arresting the movement of the slide when it is desired to suspend the action of the pump.

84. In a type-casting mechanism the combination substantially as described, for controlling the action of the pump, of a pump-lock located in the line of communication between the driving-shaft and the piston, and comprising the following elements, to wit; a driving and a driven member provided with coincident apertures; a slide carrying a pin and reciprocating in a direction to enter said apertures, to lock the driving and driven members and cause them to move in unison; 65 actuating devices provided with a yielding member for reciprocating the slide; and a con-

trollable pin arranged to be projected into the path of and arrest the movement of the slide and thus prevent the locking-pin from connecting the driving and driven members. 70

85. The combination, to form a pump-lock such as described, of the driving and driven levers arranged in juxtaposition and provided with coincident apertures; the pin riding in the driven lever and adapted to enter the driving-lever, to lock the two levers together and cause them to move in unison; the slide supporting the stem of the locking-pin; the compression-link and actuating devices for reciprocating the slide; and the stop-pin arranged in position to be projected into the path of the slide, to arrest the latter and prevent the engagement of the locking-pin with the driving-lever, said stop-pin being provided with a piston and cylinder. 80

86. In a metal-injecting apparatus for type-casting and similar machines, the combination with the melting-pot provided with an arm or channel for the metal and terminating at its outer end in a nozzle, of the detachable pump-cylinder located within the melting-pot and provided with an arm connected to the wall of the pot and containing a passage communicating with that in the arm of the pot. 90

87. The combination with the pump-actuating mechanism including driving and driven members and a movable support or slide provided with a connecting member such as a pin for locking the driven to the driving member, of actuating devices for reciprocating said movable support or slide and a plurality of independent stop-pins arranged to be projected into the path of the movable support or slide, to arrest the movement of the latter and prevent connection being established between the driving and driven members of the pump-actuating mechanism; substantially as described. 95

88. In a machine for forming and setting up justified lines of types the combination substantially as described, of the mold with its adjustable mold-blade and movable section; the type-carrier reciprocating in the plane of the movable section of the mold and furnished with a type-receiving channel and sustaining-dog; a line-channel; and an ejector operating on the type in the carrier to transfer it into the line-channel. 105

89. In a machine for producing and setting up justified lines of type, the combination of the die-case; the mold provided with a movable front section and an opposite adjustable and reciprocating mold-blade, the latter operating to adjust the width of the mold when casting and to discharge the type when completed; the type-carrier reciprocating across the front of the mold in line with the movable front section thereof, and provided with a transverse type-channel containing a yielding type-support; a line-channel; and an ejector arranged opposite the entering end of the 115 120 125 130

line-channel and reciprocating through the type-carrier, to discharge the type therefrom and transfer it to the line-channel.

90. In a machine for forming and setting up 5 lines of types the combination of the mold provided with a movable wall or section and an opposite mold-blade and adjustable to vary the width of the mold and reciprocating to eject the finished type from the mold; a 10 type-carrier reciprocating in the same path as the movable section of the mold and provided with a type-channel; a line-channel; and a pusher or ejector operating through the channel of the type-carrier to force the type 15 into the line-channel.

91. In a strip-feeding mechanism such as described, the combination with the pin-wheels and actuating devices therefor controlled by a reciprocating member or lever, 20 of opposing surfaces between which the strip is conducted, one of said surfaces being movable to clamp the strip and receiving motion immediately from the reciprocating member or lever which actuates the pin-wheels.

92. In a strip-feeding mechanism such as described the combination with the pin-wheels and actuating devices therefor receiving motion from a vibrating lever, of the fixed and movable clamping members or surfaces 25 between which the strip is fed by the pin-wheels, a rock-shaft connected to the feed-controlling lever and provided with devices, including a yielding connection, for reciprocating the movable member of the clamp.

93. The combination in a strip-feeding mechanism such as described of the two pin-wheels; the strip-supporting bar; actuating devices, including a driving-lever and a yielding connection, for the pin-wheels; the movable 30 clamping-bar; and the rock-shaft connected to the driving-lever of the pin-wheels and transmitting motion to the clamping-bar through connections including a yielding member.

94. The combination substantially as described of the strip-feeding devices; the strip-clamping devices including the supporting-bar furnished with a series of ports and the movable clamping-bar furnished with a corresponding 35 series of ports communicating with a pressure-supply; a pressure-controlling valve; and actuating devices for the feeding and clamping mechanism, and the valve, the same including the driving-lever connected to the feed-actuating devices, and a connection intermediate the latter and the valve.

95. The combination substantially as described of the pin-wheels and their actuating 40 devices; the cross-bar located between the pin-wheels and provided with a series of ports; a reciprocating clamping-bar or cross-head provided with a feeding-channel and a series of ports; the valve governing the admission 45 of fluid to the feeding-channel; the driving-lever connected through a yielding link to the pin-wheel-actuating devices; and a rock-

shaft receiving motion from said driving-lever and provided with cams for operating the clamping-bar, and an arm for operating 70 the valve.

96. The combination substantially as described of the stationary cross-bar with its series of ports; the reciprocating cross-head furnished with a corresponding series of ports 75 and a supply chamber or passage; the valve carried by said cross-head; the rock-shaft provided with an arm for engaging the valve and two cams; and the bar engaged by said cams and connected to the cross-head by bolts 80 and springs.

97. In a machine for making justified lines of type, containing as its principal elements, a movable die or matrix case, an adjustable mold, normal adjusting and justifying devices for the mold, and a perforated controlling-strip, the combination therewith of a controlling system governed by the perforated record-strip and operating controlling-stops for determining the position of the die-case, and the adjustment of the justifying 90 devices and their connection with the mold.

98. In a type-making machine, the combination of the following elements, to wit; a movable die-case; mechanism for reciprocating the die-case; a plurality of stop-pins or interceptors serially arranged; a type-mold provided with a movable mold-blade; a normal mold-blade-adjusting mechanism; an abnormal adjusting or justifying mechanism 100 for the mold-blade; a record-strip; and a controlling system embodying separate lines of communication between the record-strip and the stop-pins or die-case interceptors and the abnormal or justifying mechanism of the 105 mold-blade.

99. In a type-making machine the combination with the mold, the movable mold-blade, the movable die-case, and the die-case-actuating mechanism, of the following elements, to wit; a plurality of stop-pins or interceptors for measuring the extent of motion of the die-case; a mold-blade-adjusting mechanism; a record-strip; and a controlling system governed by the record-strip and including separate lines of communication between the record-strip and each stop-pin or die-case interceptor and between said record-strip and the mold-blade-adjusting mechanism. 110 115 120

100. In a type-making machine such as described the combination of the following elements, to wit; a type-mold provided with a movable mold-blade; a movable die-case provided with a plurality of dies or matrices; 125 a plurality of controllable stop-pins or interceptors serially arranged and operating in conjunction with the die-case-actuating devices, to center the dies or matrices opposite the mold; normal mold-blade-adjusting devices operating in unison with the die-case; abnormal adjusting or justifying devices for controlling the position of the mold-blade but normally disconnected therefrom; control- 130

lable connections for placing the justifying devices in operative communication with the mold-blade; a record-strip; and a controlling system containing separate lines of communication between the record-strip and each die-case stop-pin or controller and between said record-strip and the controllable connections governing the application of the justifying devices to the mold-blade; substantially as described.

101. In a type-making machine the combination of the following elements, to wit, a movable die-case provided with a series of dies or matrices; actuating devices for reciprocating the die-case; controllable stops or interceptors serially disposed in the line of motion of the die-case; a record-strip; and a controlling system intermediate the record-

strip and each of the controllable stops or interceptors; substantially as described. 20

102. In a type-making machine the combination of the following elements, to wit; a mold; a movable die-case furnished with a plurality of dies or matrices; actuating mechanism having a uniform motion and yielding 25 connection with the die-case; controllable stops or interceptors serially disposed in the direction of motion of the die-case; a record-strip; and a controlling system intermediate the record-strip and each stop or interceptor; 30 substantially as described.
